CARTON VENDING MACHINES AND THE LIKE
Ray M. Cope, 7624 S. Colfax Ave., Chicago, Ill.
Filed Jan. 8, 1962, Ser. No. 164,879
23 Claims. (Cl. 221—81)

This invention relates to carton vending machines, and the like. More particularly, the invention relates to improvements in machines for vending cartons of liquids, such as cream, milk, fruit juices, and other liquids. It will be understood, however, that insofar as the structure of the vending machine is concerned, it may be used for the vending and dispensing of cartons of many kinds and species. The features of construction hereinafter disclosed have been designed and built for dispensing and vending cartons of such liquids as already mentioned, taking into account the need of making provision against damage to the cartons during various operations of filling the machine with such cartons, and against failure to maintain proper and acceptable temperature conditions in the filled cartons stored in the machine, and prior to dispensing the same. Various protective features of structure will appear hereinafter, provided to ensure safe and properly controlled operations.

An important feature of the invention relates to the provision of a vending machine in which various of the operational elements are grouped into units which units are self-contained and may be inserted into and removed from the housing readily for adjustment or repair, or for substitution of other units designed to vend cartons of different size or contour from the cartons previously dispensed by the machine. In this connection the structures hereinafter disclosed include one or more racks provided with vertically travelling shelves, each such shelf being horizontal and sustaining a number of cartons set close together along its length, with provision for lowering the shelves step-by-step for sequential delivery of the supported cartons by successive operations of the machine. Conveniently, such shelves are provided in the form of flights extending transversely between two parallel chain loops, the flight-shelves moving downwardly at one face of the unit, and returning upwardly at the opposite face of the unit, the cartons being supported by the flight-shelves during downward movement of such shelves, and being delivered from the shelves at a low position, successively at termination of the successive vending operations. The empty shelves then move around the lower ends of the chain loops to the reverse, upwardly moving face of the unit, and rise, empty to the upper end of the unit and over the top of the unit, then moving downwardly at successive vending operations, during which successive vending operations such previously emptied shelves are moving down towards the vending stage. Such operations continue until the entire group of flight-shelves has been emptied. At such time an "empty" signal is given whenever such vending unit is requested to deliver a carton. These operations will be explained in detail hereinafter.

Conveniently, each flight-shelf is made of length (corresponding to the lateral distance between the two chain loops) sufficient to accommodate a number of cartons. Thus, the storage capacity of the vending unit is greatly amplified by providing flight-shelves of length sufficient to accommodate a considerable number of the cartons (with corresponding lateral distance between the two chain loops of the unit). Since it is intended to deliver only a single carton at each vending operation, it is necessary to make provision for delivering or releasing or discharging the cartons from each flight-shelf, one at a time corresponding to successive vending operations. It is also necessary to provide for advance of the supporting chains and the flight-shelves, at each vending operation, a distance less than the distance between successive flights.

2

The lessened distance of advance thus imposed is equal to the distance between successive chain flights divided by the number of cartons accommodated along each flight-shelf.

5 A prime object of this invention concerns itself with the means by which provision is made for the successive advances of the chain carrying flight-shelves such lessened distance as above defined, and for the successive delivery of the cartons carried by such flight-shelf, synchronously with each flight-shelf advance. Thus the cartons sustained by the shelf will be delivered one at a time, proceeding along the length of the flight-shelf, in regular succession from end to end thereof.

10 For a stated length of the flight-shelf (corresponding to a specified depth of the cabinet in which the units are housed, measured from front to rear), it is evident that the number of cartons which can be accommodated along each flight-shelf will depend on the size of the cartons, measured in the direction parallel to the shelf. Thus, 15 for example, small cartons, such as one-half pint size, may be accommodated, seven along each flight-shelf of a unit of specified dimension, front to rear of the cabinet. However, larger cartons can be accommodated, only 20 five along such length. Accordingly, when using the unit for accommodation of only five cartons, and with a stated 25 distance between successive flight-shelves, such flight-shelf distance must be divided by five instead of seven, to determine the proper advance to be executed by the flight-carrying chains corresponding to each vending operation. 30 It is an important feature of the present invention, that I have made simple provision for adjusting the amount of flight-chain advance by simple means, corresponding to such change in the number of cartons to be accommodated on each flight-shelf.

35 I have provided a drive motor for driving the flight-carrying chains of the unit. Such drive is effected by shaft drive from the output shaft of the motor unit (including its built-in gear-reducer), to the drive shaft of the flight-shelf conveyor unit. Such drive between these two 40 shafts is a positive drive, so that the angular rotation of the drive shaft, and of the motor output shaft, exactly corresponds to the advance which will be executed by the flight-carrying chains. Conveniently, I have provided an arrangement such that each rotation of the motor output shaft (including such built-in gear-reducer) 45 exactly corresponds to advance of the flight-carrying chains a distance equal to the spacing between successive flights. I have also provided one-cycle means to produce motor stoppage at conclusion of each motor operation, at 50 a position exactly corresponding to advance of the flight-carrying chains a distance equal to the flight-spacing divided by the number of cartons to be carried by the flight. Thus, each motor starting operation will be followed by 55 stoppage of the motor after drive of the flight-carrying chains the intended distance. Such motor stopping means conveniently includes a cam element having a number of switch operating elements equal to the number of cartons carried by the flight-shelf, together with a motor stopping control switch under control of such cam element. Thus, whenever it is desired to make provision for accommodation on each shelf of a vending unit, a stated number of cartons, a vending unit designed to accommodate such number of cartons on each of its shelves may be set into the housing, and there may be fastened to the motor output shaft a cam having a number of motor stopping positions equal to the number of cartons to be accommodated on each flight-shelf of such vending unit, such motor stopping positions being equally spaced around such cam.

60 65 70 75 80 85 90 95 In connection with the foregoing explanations it is here noted that a prime object of the invention is to pro-

vide a very versatile structure, in the sense that there may be introduced and received into a given cabinet or housing, a number of the flight-shelf carrying units, each designed and constructed to accommodate cartons of a specified size, both as to length (top to bottom), as to width (along the shelf), and depth (across the shelf). The spacing between the flight-shelves must be sufficient to accommodate cartons of the specified length without interference between the tops of the cartons and the shelf above; the width of the cartons will determine the number accommodated along a shelf; and the depth of the cartons must be accommodated within the space between the flight-shelf unit itself and any other structural element of the machine. It will presently appear that such structural element comprises a portion of the carton supporting and releasing elements. However, under present conventional practice cartons of various capacities within a considerable range of capacities, are formed to have at least one of their cross-sectional dimensions (either width or depth, or both), of standard size (e.g., 2 1/4 inches). Such being the case, the cartons may be set along the shelf close together, and turned, if necessary, into positions such that they are accommodated within the permissible depth dimension of the vending machine structure. The number of cartons along the shelf will be determined by the other cross-sectional dimension of such cartons. In addition to the foregoing, provision is, however, made for adjusting the position of each flight-shelf carrying unit laterally from or towards the structural element already referred to, when necessary to accommodate the depth dimension of the cartons placed on the shelf.

It is a further important object of the invention to make provision for readily changing the cam element of each motor drive unit, and for making further adjustments and/or changes in such motor drive unit, without difficulty. To this end such motor drive units for all of the flight-shelf carrying units are supported by a common panel which is readily rocked into horizontal position (prior to insertion of the several flight-shelf carrying units into the cabinet). In such horizontal position the elements of the several motor drive units, including their cams, are made fully accessible to the operator. Having made such changes or adjustments as needed, such panel is restored to its vertical position, whereupon the output ends of the several motor drive units are exposed in positions to receive the matching drive shafts of the several flight-shelf carrying units, for driving connection thereto. During this operation the flight-shelf carrying unit is accurately aligned with the output end of the corresponding motor drive unit. Provision is also made for lateral adjustment of each of the motor drive units, to bring it to position corresponding to any lateral shift of the corresponding flight-shelf carrying unit, such as already referred to.

A further and important feature of the presently disclosed structures relates to the means for releasing and delivering the cartons, one by one, from their support on such flight-shelf carrying units, according to the signals arriving from the coin operated and controlled elements. As already explained, the cartons are supported by the respective shelves during travel downwardly to their delivery positions. During such time, and prior to such delivery, each carton also gains lateral support against the structural element which is proximate to the vertical path of travel of the flight-shelves of the carton carrying unit in question. Such shelves are themselves so attached to the shelf carrying chains of the unit of which they comprise a part, that they are ruggedly retained against rock or tilt from a substantially horizontal position. In other words, each shelf descends step-by-step as cartons are demanded and delivered corresponding to successive vending operations, until finally any given carton reaches its level of delivery. Such delivery is produced, when demanded, by the action of an ejector

arm which is actuated by a rocking movement, to displace the carton from its shelf position, and permit it to descend. These ejector arms are located at positions aligned with vertical rows of cartons on the numerous shelves, so that each ejector arm serves, in proper timing, the cartons which come to its level during descent of the shelves. Thus there are provided as many of these ejector arms as there are cartons carried on each shelf; and during the step-by-step descent of the shelf, each carton along its length comes in turn to position for ejecting operation by that ejector arm which corresponds to the vertical row of cartons including the carton now to be delivered. This arrangement is clearly to be distinguished from any arrangement in which delivery of the cartons from a shelf position is produced by a gravity operation permitted by downward rock of the shelf, as such shelf is released and permitted to effect such rock at the delivery position. Such a rocking gravity actuated shelf arrangement is disclosed in the Bookout et al. patent, No. 2,888,165, issued May 26, 1959.

Specifically, such ejector arms are rocked for the ejection operation by downward movement of the flight-shelf carrying the carton against which such ejector arm acts, the parts being properly timed to effect ejection of the carton at the proper time, and in the proper relation to other elements of the structure.

Reference has been made to a structural element adjacent to the flight-shelf carrying chain unit. Such structural element comprises a plate abutment against which the leaning or tilting cartons carried by the several shelves abut and downwardly along which plate they slide during descent of the shelves. Such plate has its lower edge provided with steps extending horizontally opposite to the several carton supporting portions of the flight-shelf unit. Each such horizontally extending step portion is at elevation to permit the carton to rock outwardly, or to slide outwardly from the shelf by which it has been carried, to complete the delivery of such carton which is now to be released; but the horizontal steps located opposite to the downward paths of travel of the not yet to be released cartons are at successively lower levels, so that the cartons for which they are provided are released at later times, and subsequent vending operations, successively.

It is a feature of the present improvements, that I have made provision for vertical adjustment of such plate element to bring its stepped edge portions into proper relation, vertically, with the ejector elements by which the successive cartons are ejected laterally from their shelf carried positions, thus ensuring accurate and certain delivering operations for each and all of the cartons to be delivered.

A further feature of the present improvements relates to the provision of arrangements such that each such stepped plate or barrier may serve cartons carried by two of the flight-shelf carrying units, one at each side or face of such plate. Under this arrangement, cartons from the carrying unit at one side are delivered, at the proper time, beneath the step which corresponds to the vertical row of cartons served by such step, it being noted that the controls for bringing the vending elements into operation include arrangements such that it is not possible to produce more than one vending operation at a time. Thus, as each vending operation occurs, with corresponding delivery of a carton beneath a given step of the stepped plate, it is not possible to produce interference with such delivery by occurrence of a simultaneous delivery from an opposite flight-shelf of the opposite carrying unit. In this connection, however, it is also noted that provision has been made, in the present disclosures, for preventing interference between the descending, now released, carton, with a carton carried by the opposite flight-shelf of the opposite carrying unit. Such provision is desirable for the following reasons;

Some types of cartons are provided, at their upper and lower ends, with cap elements which either project

beyond the lengthwise bodies of such cartons, or are carried downwardly over a slight distance of such lengthwise carton bodies. Consequently, if, during the release and descent of a carton from the one flight-shelf carrying unit now in use, such carton should be extended laterally from its now abandoned shelf, far enough to touch the opposite carton of the opposite carrying unit, a jamming or engaging might occur, preventing the so-released carton from completing its descent, with jamming of the machine, and requirement of a servicing operation, as well as loss of the prepaid price for such so-released and partially delivered carton. I have, accordingly, made provision in the hereinafter disclosed structures to prevent any such lateral interference between cartons of proximate carrying units, notwithstanding that during each releasing and delivering operation the released carton intrudes onto the space assigned to its opposite neighbor.

It is also to be noted that by this arrangement it is possible to bring the successive flight-shelf carrying units closer together than would otherwise be possible, since a portion of the space between two such carrying units is used by both such units during their delivering operations. Furthermore, by the presently to be disclosed arrangements a single one of the stepped plates or barriers serves two of the flight-shelf carrying units, thus doubling its beneficial function.

Reference has been made to the need of properly timing and synchronizing the positions of the horizontal steps of the stepped plate or barrier, with respect to the arrivals of the flight-shelf elements at positions where the corresponding ejectors act to deliver the cartons laterally from support by the shelves. Each of the stepped plates or barriers is vertically adjustable with respect to the carrying units. However, since such single stepped plate serves carrying units at both sides, it becomes necessary to ensure that when proper synchronization of such stepped plate with one of the carrying units has been made, proper synchronization of the steps of such stepped plate with respect to the companion carrying units flight-shelf elements will also occur. To this end I have made provision for enabling adjustment of the rotated position of each of the carrying units' drive shaft, with respect to the motor output and cam elements of the motor corresponding to such carrying unit, so that after other adjustments have been made, it is possible, by a simple operation, performed by the service person, and at the front portion of the carrying unit, to produce the desired exact synchronization of operations. Thus both of the carrying units served by such single stepped plate are brought into exact synchronization of their several operations.

Means are provided for refrigerating the cabinet which houses the units and elements already referred to. In this connection I have so arranged the several operational elements and units comprising the releasing and delivering mechanisms that they may be readily removed from and inserted into a chamber within the cabinet, and brought into adjusted conditions by simple and convenient operations, with such operations limited to the carrying units and immediately related elements. It is now noted that the released and delivered cartons descend to a hopper, and when there are provided more than a single flight-shelf carrying unit, such hopper is designed and built to underlie all of such plurality of units, thus causing all of the cartons delivered from all of the units to come to a common discharge location. In this connection, I have provided a delivery door in position for enabling the customer to reach into such hopper and remove the delivered unit or units therefrom. Such elements are so designed and built that when the door is opened the hopper is shifted into position convenient of access through the open door; but at the same time, such hopper is then in a position such as to prevent improper reaching of the hand upwardly therethrough to a position where one or more additional cartons could be hand released

and delivered. Thus the arrangement serves to prevent improper carton deliveries.

The camber already referred to, which houses the several carrying units, comprises a space above the refrigerating units. Such space is largely open for free movement of air through its body. A main door gives access to such space when necessary, by use of suitable unlocking elements. The refrigerated air is delivered up into such space, directly from the refrigerating unit, circulates through the entire body of such space, and is returned into the space beneath such chamber and where the refrigerating unit is housed. Accordingly, I have made provision for circulating the refrigerating air directly from the refrigerating unit, into and through such chamber, and finally down into the refrigerating unit space, for recirculation.

Conventional coin operated and controlled elements are provided for pre-paying the selected cartons to be delivered. The circuitry provided in connection with such coin operated and controlled elements includes a "high temperature" thermostatically operated switching element, and circuitry to stop coin receiving and operational elements when the temperature of the space within which the cartons are stored rises above a predetermined point, thus complying with pure foods and other legal requirements. Such circuitry also includes provision for terminating coin receiving and operational elements when coin deposits are made corresponding to carton carrying units which have been completely depleted of their cartons. Features in connection with the circuitry will be disclosed hereinafter.

Other objects and uses of the invention will appear from a detailed description of the same, which consists in the features of construction and combinations of parts hereinafter described and claimed.

In the drawings:

FIGURE 1 shows a typical front elevation of a unit embodying the features of the present invention, being an embodiment which includes four of the carton flight-shelf carrying units;

FIGURE 2 shows a right-hand elevation corresponding to FIGURE 1;

FIGURE 3 shows a front elevation looking at the interior of the cabinet with the main door removed to reveal the interior elements and units; and this figure is on larger scale than that of FIGURES 1 and 2; and in FIGURE 3 there are shown cartons carried by three of the carrying units, the right-hand unit being exhausted and empty; and this figure also shows the front elevation of the compartment directly beneath the carton carrying unit compartment, the door of such lower compartment being removed to reveal the carton delivery chute which leads to the hopper connected to the delivery door (removed); and FIGURE 3 may be considered as a section taken on the line 3-3 of FIGURE 2, looking in the direction of the arrows;

FIGURE 4 shows a front elevational view of the lowermost compartment which houses the refrigerating compressor unit and accessories; and this figure is a lower continuation of FIGURE 3, and on the same scale as FIGURE 3;

FIGURE 5 shows a face view of one of the carton carrying units on the same scale as that of FIGURES 3 and 4; and may be considered as a section taken on the line 5-5 of FIGURE 3, looking in the direction of the arrows, but without the presence of the cartons shown in FIGURE 3;

FIGURE 6 shows, on enlarged scale as compared to FIGURES 3 and 5, the lower portion of one of the carton carrying units, a portion of such unit being broken away to shorten the figure; and this figure shows in more detail the ejecting units corresponding to the vertical rows of carton positions;

FIGURE 6A shows a detail section through the paddle

plate taken on the line 6A—6A of FIGURE 6, looking in the direction of the arrows;

FIGURE 7 shows a left-hand elevational view corresponding to FIGURE 6;

FIGURE 8 shows a right-hand elevational view corresponding to FIGURE 6;

FIGURE 9 shows a longitudinal section through the drive shaft which is located along the upper portion of a carton carrying unit; and may be considered as a section taken on the line 9—9 of FIGURE 10, looking in the direction of the arrows;

FIGURE 10 shows a view of the upper portions of the carton carrying unit shown in FIGURE 6, and it may be considered as an upward extension of that FIGURE 6 with a portion centrally of the unit broken away;

FIGURE 11 shows a left-hand end view corresponding to FIGURE 10;

FIGURE 12 shows a horizontal cross-section taken on the line 12—12 of FIGURE 11, looking in the direction of the arrows;

FIGURE 13 shows a right-hand end view corresponding to FIGURE 10;

FIGURE 14 shows a horizontal cross-section taken on the line 14—14 of FIGURE 13, looking in the direction of the arrows;

FIGURE 15 shows a face view of the lower portion of the stepped plate which is located between and serves two of the carton carrying, flight-shelf units, the central portion of the structure being cut away to shorten the figure; and in this figure the flight now to be served is shown behind such stepped plate, and the several ejector units are shown in their positions with respect to such flight, and cartons supported by the shelves are also shown by dashed lines; and this figure may also be considered as a section taken on the line 15—15 of FIGURE 3, looking in the direction of the arrows;

FIGURE 16 shows, schematically, the relations of the shelves of the two opposing carrying units, and the manner in which the intervening stepped plate serves cartons supported by shelves of both of the carrying units; and in this figure the lowermost shelf of the right-hand carrying unit is shown in two positions, one a full line position, and the other, succeeding position being shown in dotted lines; and this figure shows how, during descent of the flight during a delivering and ejector operating movement the carton is shifted outwardly from its position of support by the flight to a delivery position, and also shows how, during such operation the tilt of the carton may be reversed to enable it to slide readily from the shelf, and be delivered downwardly to the receiving hopper;

FIGURES 17, 18 and 19 show, schematically three consecutive positions of the downward movement of the shelf during a delivering operation, being the lowermost shelf of the left-hand carrying unit; and this figure shows corresponding carton positions during the shelf descent, with final slide of the released carton from its support on the shelf, past the carton of the companion carrying unit, and towards the receiving hopper;

FIGURE 20 shows, on enlarged scale as compared with FIGURES 6 and 15, that portion of the flight which comprises a carton shelf, together with the ejector element and the stand to which such ejector is pivoted, the ejector element being shown in its normal or non-ejecting position;

FIGURE 21 shows a cross-section taken on the line 21—21 of FIGURE 20, looking in the direction of the arrows; and this figure shows the rearwardly extending cam element on the ejector arm, which cam element is engaged by the descending flange of the flight during the releasing and delivering operation, to rock such ejector element rightwardly as shown by the curved arrows, far enough to carry the lower edge of the carton to and beyond the edge of the shelf, thus releasing such carton for downward delivery;

FIGURE 22 shows a top or plan view of the left-hand end portion of one of the flights; and the intended locations of two of the cartons supported by such flight are indicated by the legends "A" and "B"; it being noted that in each case the flight is provided with an ejector receiving slot located centrally of the intended location of the carton;

FIGURE 23 shows a vertical front face view corresponding to FIGURE 22;

FIGURE 24 shows a horizontal section taken on the line 24—24 of FIGURE 23, a looking in the direction of the arrows;

FIGURE 25 shows an end view corresponding to FIGURES 22, 23 and 24;

FIGURE 26 shows a cross-section taken on the line 21 of FIGURES 22 and 23, but without inclusion of the ejector element; and this figure also shows the lower corner portion of a carton in place on the shelf;

FIGURE 27 shows a face view of one of the stepped plates which are located between companion pairs of the carrying units; such stepped plate being provided with downwardly extending flaps which are laterally deflectable in either direction, and serve to prevent interference between a presently being delivered carton and a carton carried by the companion and opposite carrying unit at a location opposite to that of the now being released and delivered carton; the central portion of the stepped plate being cut away to reduce the height of the figure;

FIGURE 28 shows a top edge view or a section through the stepped plate shown in FIGURE 27, taken on the line 28—28 looking in the direction of the arrows;

FIGURE 29 shows a left-hand edge view corresponding to FIGURE 27;

FIGURE 30 shows a face view of the partition which is included vertically in each of the carrying units to ensure prevention of interference between the oppositely moving runs of the two flight-carrying chains of a carrying unit;

FIGURE 31 shows a horizontal section taken on the line 31—31 of FIGURE 30, looking in the direction of the arrows;

FIGURE 32 shows a front elevation of the driving motor unit which is provided for all of the driving motors of the several carrying units of the assembly, three of the motor plates being shown in place on such unit, and the fourth motor plate having been removed from the unit to show the opening which is provided for insertion of the motor-reduction gear assembly backwardly through such opening;

FIGURE 33 shows a top plan view corresponding to FIGURE 32;

FIGURE 34 shows a cross-section taken on the lines 34—34 of FIGURES 32 and 33, looking in the directions of the arrows; and in this figure the operational position of the unit is shown by full lines, and also a portion of such unit is shown in its forwardly rocked position by dotted lines, being the horizontal position to which such unit may be rocked when it is desired to gain access to the several drive motors and corresponding cams, etc;

FIGURE 35 shows a fragmentary face view of the vertical end post of one of the carrying units, being a section taken on the line 35—35 of FIGURE 36, looking in the direction of the arrows; and this figure shows the cross-pin and slot connection between the driving motor output shaft and the drive shaft of the carrying unit;

FIGURE 36 shows a cross-section taken on the line 36—36 of FIGURE 35, looking in the direction of the arrows; and this figure shows details of the journal of the drive shaft of the carrying unit in the end post of such carrying unit proximate to the output shaft of the corresponding drive motor;

FIGURE 37 shows a face view of one of the stopping control cams, being provided with seven stopping positions around its periphery, corresponding to an installa-

tion in which seven cartons are supported on each flight element;

FIGURE 38 shows a fragmentary vertical section taken on the line 38—38 of FIGURE 1, looking in the direction of the arrows, but on enlarged scale as compared to FIGURE 1; and FIGURE 38 shows the carton delivery chute which receives all of the cartons delivered from all of the carrying units and delivers such cartons to the hopper which is controlled by the vendor's receiving door when such door is opened; the door and the hopper being shown in door closed position by full lines, and in door opened position by dashed lines; and this figure also shows, schematically, the refrigeration cooling unit behind such door-hopper unit, such cooling unit serving to deliver the cooled air upwardly through a chute into the space of the carrying unit chamber behind such carrying units, for circulation throughout such chamber;

FIGURE 39 shows a modified form of stepped plate assembly which includes a modified form of the flaps which extend down between cartons of the two companion carrying units;

FIGURE 40 shows a vertical central section taken on the line 40—40 of FIGURE 39, looking in the direction of the arrows;

FIGURE 41 shows in face view one of the arms of the flap unit shown in FIGURES 39 and 40;

FIGURE 42 shows a cross-section taken on the line 42—42 of FIGURE 41, looking in the direction of the arrows;

FIGURE 43 shows a modified form of slot to enable introduction of the flap unit of FIGURES 41 and 42, through the stepped location of the stepped plate;

FIGURE 44 shows, schematically, two oppositely located cartons carried by flight-shelves of the oppositely companion carrying units, with a flap unit of the type shown in FIGURES 39, 40, 41, 42 and 43 separating such two cartons;

FIGURE 45 shows, schematically, a wiring diagram of a vending unit embodying the features herein disclosed; the details of the coin receiving, testing, collecting, and rejecting elements not being shown, as they are largely of conventional type.

FIGURE 46 shows, schematically, and in outline, a modified embodiment of the shelf-flight in its travel over the path including the upper and lower sprockets, and this figure shows a series of successive flight positions during such travel;

FIGURE 47 shows a cross-section through one of the modified form flights shown in FIGURE 46; being that embodiment in which only the upper chain supported pin is used as a pivot on which the flight may rock; such rock under urge of the load carried by the flight being limited at the horizontal position of the flight; and

FIGURE 48 shows a cross-section through another embodiment of the flight wherein only the lower chain supported pin is used as a pivot on which the flight may rock; such rock under urge of the load carried by the flight being limited at the same horizontal position as is imposed by the embodiment of FIGURE 47, but with the rock limiting abutment properly located to meet the requirements imposed by use of the lower as the pivot.

I shall first describe the carton carrying unit in which the cartons are stored, and from which they are displaced and delivered one at a time. Thereafter I shall describe the various units which are associated and combined with such carrying unit, to produce the desired ensemble of a complete coin operated unit.

The carton storing unit is shown in face view in FIGURE 5, and various details of its construction are shown in FIGURES 6 to 14, and FIGURES 22 to 26, inclusive. The functional and delivering operations by which the individual cartons are delivered from such storage unit are also shown in FIGURES 6, 15 to 21, inclusive, and FIGURES 26, 27, 28, 29, inclusive, and a modified em-

bodiment of the stepped plate is also shown in FIGURES 39 to 44, inclusive. Reference is now made to these figures as follows:

Each storage and carton carrying unit includes the front and back vertical end struts, 50 and 51, respectively. These are conveniently secured to the top and bottom horizontal elements 52 and 53 to produce a rectangular form of height to accommodate a number of horizontal shelf elements, lying in two vertical laterally displaced planes; and each such shelf element is adapted to store a number of cartons along its length, measured from front to rear, depending on the front to back dimension of such shelf element, and the size of the cartons stored thereon. These shelf elements are connected at their front and back ends to corresponding chains which travel over top and bottom sprockets suitably journaled with respect to the vertical struts. In FIGURE 5, and elsewhere, each shelf is numbered 54, and when describing and considering the relationship of proximate carrying units and their stored cartons, to each other, I shall include the suffix "a" to cartons of one such unit, the suffix "b" to cartons of the proximate unit, etc. Each such shelf is of generally channel cross-section, as well shown in FIGURES 22, 23, 24, 25 and 26, including the upper flange 55 and the lower flange 56, and the end portions of such shelves are provided with the end plates 57 (see FIGURES 23, 24 and 25) which lend rigidity to the shelf element, and also provide elements to which the supporting studs and rollers, presently to be described, are connected, and by which the shelves are connected to the runs of the chains. These details will be explained presently.

Examination of FIGURES 22 to 26 will also show that the lower flanges of such shelf elements project laterally from the webs 58 of the channels farther than the upper flanges, to thus provide carton supporting lower flange portions for cartons resting thereon, and with such cartons extending upwardly past and beyond the levels of the upper flanges of the shelves. This will be further discussed hereinafter.

The vertical struts 50 and 51 are of cross-section as shown in FIGURES 12 and 14. Each such strut is of generally channel section, and of lateral width sufficient to accommodate the lateral spacing of the vertical runs of the chains, and the shelves carried thereby. The connections of the ends of the shelves to the chains are effected by the following means:

A pair of pins 59 and 60 are extended through each of the shelf end plates 58 (see FIGURES 6, 12 and 14), and project outwardly far enough for connection to corresponding links of the proximate chain. (Such pins, for each such end plate 58 are seen to be in vertical alignment, whereas, in FIGURES 12 and 14 only the upper pin of each such pair is shown.) The vertical runs of the several chains are received in partially closed vertical channels, 61 and 62, the flanges of such channels being formed towards each other, but with a narrow slot left between their proximate edges. The pins 59 and 60 extend through such slots to the interior of the channels; and small, flanged rollers 63 and 64 are journaled on the pins, with their grooved edges receiving the edge portions of the flanges of such channels 61 and 62. Since the pins 59 and 60 of each of the shelf end plates are vertically displaced, so that the rollers on such pins are also vertically displaced, it follows that during vertical travel of a shelf carried by such pins and rollers, and the chain to which the pins are connected, the shelf channel is prevented from rocking about a horizontal axis (except when the chain is travelling around one of the end sprockets); thus such shelf is caused to travel vertically, either down or up, while retaining its flanges 55 and 56 in horizontal position. In other words, there is no rock of the shelf possible during vertical travel of such shelf, either downwardly during the intended movement of the supported cartons towards the delivery stage, or upwardly,

during the returning travel of the shelf to its top sprocket supported position. Accordingly, it is not possible to deliver or discharge the supported cartons from such shelf, by any rocking movement, and other means, presently to the disclosed, are provided to ensure discharge of each carton at its intended delivery position, and under proper coin or other payment, control. Such delivering and discharging means will be disclosed fully hereinafter.

In FIGURE 3, which is a front elevational view of the interior of the refrigerated carton storing chamber, there are shown, in end elevation, four of the carrying units, designated "I," "II," "III," and "IV," respectively. In this figure the vertical runs of the chains at the fronts of such carrying units are also shown by the dash-dot lines; and such chains travel over upper and lower sprockets 65 and 66, also shown by the dash-dot circles in that figure. These sprockets are journalled closer to that face of the carrying unit at which the cartons are travelling down, than to the opposite, or upwardly returning shelf face of such unit, as clearly evident from examination of such FIGURE 3, and other figures. Thus, during the downward movement of a shelf its lower or carton supporting flange projects laterally from the carrying unit farther than its projection during the upward or returning travel of such shelf. Accordingly, when two of such carrying units are placed back to back, as shown by the units II and III of FIGURE 3, they may be set closer together without interference between projecting shelf flanges of the two carrying units, than would be possible otherwise. Thus, the overall width of the cabinet or other enclosing structure may be correspondingly reduced, without sacrifice of space needed for accommodation of cartons of given size.

Referring to FIGURES 3, 9, 10, 11 and 13, there is shown the horizontal drive shaft extending from front to back of each of the carrying units, being numbered 67 in its entirety. Such shaft carries the sprockets 68 and 69 at its front and its back portions; and the chains 62 travel over and mesh with such sprockets for drive. The construction of such drive shaft is shown in detail in FIGURE 9, and is as follows:

The shaft proper comprises a tubular element 70, shouldered at 71 and 72 near its front and rear ends, the sprockets being set against such shoulders and drivingly connected to the tube. A rod 73 extends through the tube with its front end projecting forwardly to the front end of the tube, as shown at the right-hand of FIGURE 9. Beyond the front sprocket 68 such rod is grooved as shown at 74, and a set screw 75 is threaded through the overlying portion of the tube, with the inner end of such set screw engaged with the groove. By tightening such set screw the tube and rod may be drivingly locked together; but by loosening the set screw the tube may be rotated to a new angular position with respect to the rod, thus bringing these parts into a new angular relationship. Thereafter, by again tightening the set screw, the rod and tube may be drivingly locked together in their new angular relationship. A stiffening ring 76 may be set onto the tube at the location of such groove and set screw, with the set screw extended through such stiffening ring, as shown in FIGURE 9. At its right-hand end the rod is drivingly connected to a fixture 77 which is end slotted at 78 to receive the cross-wise extending pin of the low speed output shaft of a drive motor, presently to be described. At this point I will state, however, that I have provided a drive motor corresponding to each carrying unit, each such drive motor having a low-speed output shaft which drives through the instrumentality of such cross-wise extending pin. I have also made provision for the stopping of each such motor at successive definite angular positions of its output slow speed shaft and cross-wise extending pin, with corresponding stoppage of the vertical movement of the chains engaged with the sprockets of the shaft 70 driven by such

motor. The angular adjustability of the shaft tube in relation to the corresponding rod, makes it possible to adjust the vertical stopping positions of the shelves on the chains of the carrying unit in question. Thus each carrying unit may be caused to stop with its shelf now to deliver a carton, at exactly the correct position for effecting such delivery. The importance of such adjustability will appear hereinafter. It is also noted that such angular adjustability is effected at the front end of each drive shaft, and such adjustment may be made after the entire unit has been assembled without need of effecting adjustments of other elements.

The rod 73 is journalled at the points where it passes through the vertical struts 50 and 51. Such journalling is conveniently effected as shown in detail in FIGURES 35 and 36. To this end a grommet 79 of rubber or other elastic material is set into a hole through the web of the vertical strut at the proper location to accommodate the drive shaft; and an oilless bearing 80, set onto such shaft, is set into the central opening of such grommet. By this arrangement, any slight misalignment of parts may be compensated by the elasticity of such grommet, it being noted from examination of FIGURE 5 that such vertical struts are intended to be secured to the top and bottom horizontal elements, and that any slight departure for right-angularity of the struts with respect to the top and bottom elements 52 and 53 is thus compensated for by such grommet arrangement.

In order to prevent possible interference between the back portions of the several shelf units carried by the lowering and rising runs of each chain loop, I have shown the barrier plate 81 set through the chain and shelf elements of each unit, such barrier plate extending between the two vertical struts of each carrying unit, and having its vertical edges set against the proximate faces of the struts and secured thereto, as shown in FIGURES 12 and 14, and elsewhere; such vertical edges being flanged as shown in such FIGURES 12 and 14 for flat engagement with the proximate struts.

Examination of FIGURE 3 and other figures shows that although the cartons supported by the various shelves rest on the longer flanges 56 of the shelves, still such flanges, in the embodiment shown in the drawings, do not extend outwardly from the carrying unit far enough to do more than take the vertical component of weight, and do not of themselves prevent lateral or outward rock of the cartons from such shelf flanges. Under these conditions it is necessary to make provision for limiting such outward rock or swing, while at the same time making provision for delivering each carton laterally outward from the carrying unit shelf at the exact delivery position intended, and as a portion of the coin pre-pay operations. The following instrumentalities have been provided to meet these requirements:

Reference to FIGURE 3 shows the presence of a carton supporting plate 82 set vertically in proximity to the carton supporting flanges 56 of a carton carrying unit, such plate 82 being separated from the carrying unit at such distance that the cartons supported by the flanges 56 of the shelves may lean outwardly from the carrying unit in question, with their lower ends supported by the flanges 56 and their upper portions in lateral supporting engagement with such plate. At this point I mention that each carrying unit is set laterally from the corresponding plate 82 a distance proper to accommodate cartons of a specified size, and with such a cartons at an angle of tilt proper to allow the desired carton delivering operations to be performed as hereinafter explained in detail. During step-by-step descent of the shelves toward the delivering position, the cartons continue to slide down while in engagement with such plate, until the delivery operation occurs, as hereinafter explained.

As shown in FIGURE 3, and elsewhere, each of the plates 82 serves carton carrying units at both of its faces, thus materially reducing the overall width of the cabinet

or other unit which includes a number of the carrying units. Therefore it is convenient to provide means to retain such plate 82 in a fixed position laterally of the cabinet. Then, in order to accommodate cartons of varying sizes, which require different spacings of the carrying units from the plate or plates 82, I have provided simple means to permit lateral shift and locking of each carrying unit within the cabinet, to meet such varying spatial requirements. Thus, in case the two carrying units facing the opposite sides of the plate, should be selected to store and deliver two different sizes of the cartons, one of such carrying units may be shifted laterally to a new position, or both of the carrying units may be shifted laterally to new positions, leaving the plate 82 in its fixed position between the carrying units, as before. Such lateral adjustment of each carrying unit is provided by the following means.

The upper and lower edge portions of the carrying units are provided with elements cooperating with the upper and lower cabinet or stationary frame members, to retain such carrying units stationary during intended storage and dispensing operations. I have provided means to enable lateral shift of each carrying unit, with respect to its companion plate 82, and for then locking such carrying unit in its laterally shifted position. To this end I have provided a short front to back extending flange 83 on the upper edge portion of each carrying, which flange may be shifted endwise into engagement with either of two companion slots opening downwardly in the upper portion of the cabinet or other stationary element. Likewise, I have provided on the lower edge portion of each carrying unit a pair of downwardly extending spaced apart flanges 85, providing between them a downwardly open slot, together with two upwardly extending, front to back reaching, flanges, spaced apart a distance equal to the spacing between the slots 84. Thus, by withdrawing the carrying unit forwardly from its intended working position in the cabinet, the flange 83 at its upper edge, and the flanges 85 at its lower edge, may be disengaged from the previously engaged slot 85, and from the previously engaged flange 86, respectively. Then, by lateral shift of the carrying unit the distance between the two slots 84 (which is also the distance between the two flanges 86), such carrying unit is positioned for shift backwardly to restore it to intended working position in the cabinet, but with its spacing from the plate 82 correspondingly changed. Provision has been made for securing the carrying unit in either of its intended positions by use of a wing nut or the like, extended through the opening 87 provided in the angle section 88 secured to the flange 83 and engaged with a suitable element or stationary part.

It is here noted that such a lateral shift of any of the carrying units also results in corresponding lateral shift of the drive shaft 67 whose construction has been previously described. Accordingly, without provision for corresponding lateral shift of the motor and its low speed output shaft, the drive shaft of the carrying unit will now be out of alignment with such motor's output shaft. I have accordingly made provision for also shifting the motor of such carrying unit laterally of the device into a new position where the desired condition of lateral alignment between the two shafts will occur. I shall hereinafter describe such motor shifting arrangement in detail.

Reference is next made to FIGURE 15 (which is a section taken on the line 15-15 of FIGURE 3, looking in the direction of the arrows) and shows the form of the plate 82a in its relation to the lowermost shelf element of the carrying unit I of such FIGURE 3, and also shows the manner in which the successive cartons carried by such shelf are progressively brought into positions relatively to such plate, that they may be released and delivered from the shelf, one at a time. In FIGURE 15 there are also shown five out of seven cartons carried by the shelf there illustrated, it being understood that the showing that

figure has been shortened by the front to back distance occupied by the cartons which would be legended as "C" and "D," the figure actually showing only the cartons "A," "B," "E," "F" and "G." These seven cartons are to be progressively released and delivered by step-by-step downward advances of the shelf, corresponding to like advances of the drive shaft 67, and like advances of the low speed output shaft of the corresponding motor unit.

10 In FIGURE 15 I have also shown that shelf element from which the cartons are to be delivered, designated as 89. The cartons supported by such shelf are shown schematically by dotted lines, all extending in a horizontal row along the length of the shelf. The lower edge of the plate 82 is formed to provide the successive steps 90a, 91, 92, 94, 95, and 96 (steps 90 and 93 not being shown). These successive steps are located at vertical advances equal to the full movement downwardly of the shelf necessary to discharge the full complement of cartons carried by the shelf when filled, divided by the number of the cartons carried by the filled shelf. Thus, in the illustrated embodiment, the vertical distance between the step 90a and the step 91 is one-seventh of the distance between successive shelf elements. Accordingly, the advance to 15 be executed by the drive shaft 67 (and by the low speed output shaft of the motor unit for the carrying unit in question) must be proper to advance the chains 62 of such carrying unit downwardly a distance equal to one-seventh of the distance between successive shelves, for 20 each coin pre-pay operation of the device. Conveniently, the sprocket size, and the tooth and link spacings of the chains of the carrying unit are so proportioned that one rotation of the drive shaft will produce chain movement equal to the distance between successive shelves. 25 Then, by providing for stoppage of such drive at successive advances, each equal to one-seventh of the distance between successive shelves, the proper advances of the shelf, for successive deliveries of cartons therefrom, will 30 be produced. I have made such provision for stoppages at such positions, as will presently appear.

Referring next to FIGURE 16, I have therein shown schematically, the manner of delivery of each carton from its position on the shelf. In this figure the plate 82 is shown between the two carrying units (I and II), and 35 two successive shelves 89a and 89a', and 89b and 89b', are shown, corresponding to the two carrying units. Each carton rests on the lower flange of its shelf 56, but due to the fact that, as thus supported, such carton will tend to fall away from the shelf, it is laterally supported by engagement with the plate 82 when such carton has tilted far enough to engage such plate. It is also seen that the 40 upper flange 55 of the shelf serves as an abutment against which lateral movement of the lower portion of the carton is arrested during such tilt. Thus, each carton, during its 45 descent with the chains, it retained in its intended tilted condition, until it reaches a position just above its intended delivery position. Thus, in FIGURE 16, the carton "A'" is resting with its upper edge against the plate 82 at a position just above the lower step edge 90, so that such carton, not 50 yet delivered, will be released and delivered shortly after commencement of the downward movement of the shelf at the next pre-delivering operation. I have also shown, in FIGURE 16, the approximate position of the center of gravity of such carton in its then position, by the point 55 97. I have also shown in such figure, by the dotted lines "A'" a reversed tilt position of the carton, corresponding to a lowered position of the shelf, shown by the dotted lines. In such lowered and reversed tilt position of the carton it is possible for it to slide off from the shelf, moving laterally away from the shelf, and downwardly, finally 60 sliding between the lower step edge 90 and the lower shelf flange 56, for completion and delivery of the carton to the receiving hopper. These operations will be further discussed hereinafter. The center of gravity of the carton in such reversed position is shown by the point 97', 65 70 75

slightly inwardly towards the shelf location, as compared with its previous location.

I have provided means for positively shifting the carton outwardly on the lower shelf from its position "A" to its reversed position "A'", to ensure positive release from the support of such lower shelf flange. Such means will be disclosed hereinafter, as follows:

Corresponding to each carton position on the shelf, and therefore, also corresponding to each of the column of vertically aligned cartons on the shelves above the lower-most shelf 89, there is an ejector unit. These units are numbered 98^a, 98^b, 98^c, 98^d, 98^e, 98^f and 98^g, respectively, corresponding to the successive cartons along the shelves, the unit 98^e not being shown in FIGURE 15, and the units 98^c and 98^d, also not being shown in such figure, due to the shortening of the figure. Each such unit includes a vertical stand carried by the floor of the chamber wherein the cartons are stored. These stands are numbered 99^a through 99^g. Each such stand has pivoted to it an ejector arm 100, pivoted on the cross pin 101. The general form of such ejector arm, and its relation to the stand and to the descending shelf element, are shown in FIGURES 20 and 21, and others. Reference is also made to FIGURES 22, 23, 24, 25 and 26 in considering this ejector unit construction, and its mode of operation.

From the above figures it is seen that each stand extends upwardly at a position which intersects the descending shelves of the carrying unit; and to accommodate this condition each such shelf is provided, at the location of each of the ejector units, with inwardly extending notches 102 and 103 in its lower and upper flanges 56 and 55, respectively. Examination of figures above listed shows that both these lower and upper flange notches are of width slightly greater than the width of the ejector unit stand corresponding to the carton positions of such notches, so that as each carton carrying shelf descends, step-by-step, when it reaches a lowered position at the height of the ejector stand at each carton location, such ejector stand is received by such notches without interference between the stand and the flanges of such shelf element. Also, during such operations each carton carried by a shelf moves down without interference from the corresponding ejector stand, the carton moving down, step-by-step at the outside face of the stand as evidenced by comparison of the lower left-hand carton in each of FIGURES 17, 18 and 19.

Examination of FIGURES 20 and 21 showing details of the ejector arm of an ejector unit, shows that such arm is provided with a rearwardly extending tail 104 having a cam form upper edge 105. This tail reaches rearward far enough to be engaged by the descending upper flange edge at the inner end of the notch 103, thus driving the ejector arm rightwardly towards and into engagement with the lower portion of the carton supported on the shelf flange 56. Then, as downward movement of the shelf continues to completion of the delivery movement, the ejector arm is smoothly rocked rightwardly (in FIGURE 21) far enough to shift the lower surface of the carton off the flange 56, and permit downward movement of the carton at commencement of its delivering operation. At a later time the shelf will have moved down far enough to descend below such cam element 104, with release of the ejector arm, and return of such arm to its original, full line position, shown in FIGURE 21. Such return movement will occur at a timing sequence depending on the proportioning of parts; but it is here noted that a preferred design is one in which such cam release will not occur prior to or even at completion of the carton delivering operation in question, but will occur during a further downward movement of the shelf, comprising a portion of the carton delivering movement next occurring after completion of the delivering movement now in progress. In other words, under such preferred proportioning and relation of the parts, after a given carton has been released and delivered, the corresponding ejector arm will

still be retained in its rightwardly rocked position, shown by the dashed lines in FIGURE 21, thus blocking any possible shift of the next to be released carton laterally on the shelf, and into the position now vacated by the just delivered carton. In this connection it is seen from examination of FIGURE 22, and other figures, that each carton (two being designated by the letters "A" and "B") occupies a position directly in front of the corresponding ejector unit, including the ejector arm, such fact being evidenced by the locations of the notches 102 and 103 in the flanges of the shelf element. In connection with the foregoing retention of the ejector arm of the just released and delivered carton from its position, the following condition is noted:

Upon release and delivery of the carton "A" (FIGURE 22), for example, the shelf element has been lowered far enough to permit such release and delivery, but the lower step edge 91 (FIGURE 15) of the next carton position is low enough to still prevent release of the next carton "B," since the stoppage of the down travel of the shelf element at conclusion of the releasing and delivering of carton "A," leaves such shelf high enough to prevent release of the carton "B," and normally such release of such carton "B" cannot occur until the next downward movement of the shelf occurs. But, in the absence of any blocking means adjacent to the location of such carton "B," such carton might, by jarring of the cabinet or otherwise, be shifted into the position now vacated by delivery of carton "A." Having thus shifted such carton "B" improperly into the vacated position for carton "A," such carton "B" might readily be delivered, either completely or partly from the shelf, thus either producing an improper and unpaid delivery, or jamming the machine by partial delivery of such carton "B." All such results are avoided by retaining the ejector arm of the just operated ejector unit, in its outwardly swung position until the next lowering operation of the shelf element.

Referring again to the fact that each of the plates 82 serves a carrying unit at each side thereof, reference is next made to FIGURES 16, 17, 18 and 19, and others; with specific reference to the sequence of movements produced during each releasing and delivering operation, and with reference to avoidance of cross interference between cartons carried by the two shelves of the two proximate carton carrying units. It has been mentioned that the plate 82 prevents such cross-interference, but further exploration of the relations is now proper, as follows:

In FIGURE 17 shelves of the two carrying units I and II are shown in horizontal alignment, being both stopped at their previous delivery positions. Accordingly, the two cartons "A^I" and "A^{II}" stand directly opposite to each other, their shelves being stationary. Since the lower edge of the plate 82 is only slightly below such stationary carton position, it follows that shortly after commencing the downward movement of the shelf for delivery of the carton A^I, for example, such carton could shift laterally, or become overturned, and then during its descent from its shelf element come into interfering relation to the still stationary carton A^{II}, thus either jamming the machine, or possibly shifting the carton A^{II} into a delivering position. In FIGURES 17, 18 and 19 I have shown the cartons carried by the carrying unit II as of that type in which the upper and lower ends are provided with encircling ribs or flanges 106 and 107, respectively. Such flanges thus present surfaces against which the lower edge portion of the descending carton A^I might jam, with corresponding prevention of a full delivering operation, and jamming of the machine. I have therefore made the following structural provisions:

In the embodiment shown in FIGURES 16, 17, 18 and 19 I have shown the downwardly pendant skirts 108 at the lower edges of the steps of the plate 82, such skirts being of form, and so suspended from such lower edges, that they may swing laterally of the plate 82, as shown in FIGURE 19. In the embodiment of these figures, such skirts

are of thin material, and are shown as hinged to the lower edges of the steps of the plate 82. Such hinging is of form to permit lateral swing of sufficient angle to meet all requirements such as previously explained. With this arrangement the definite cut-off position of the lower edge of the step of the plate 82 is not lost or marred, and thus exact position of commencement of release is still provided. As the shelf element continues to descend, after commencement of such descent for a delivering operation, and during the outward swing of the ejector arm produced by such shelf descent, the carton is shifted laterally and against such skirt, swinging the skirt far enough to permit the delivery of the carton from its shelf; and with subsequent sliding movement of the carton from the shelf and past the lower portion of the skirt, to the carton's fully delivered position. After such carton delivery the skirt will swing back by gravity to its central and vertical position, as shown in FIGURE 17.

Examination of FIGURE 19 also shows that such skirt is of sufficient vertical dimension to provide a barrier between the now being delivered carton A^I and its opposite carton A^{II}, for the full delivering operation. Thus such skirt extends from a position at the lower edge of the step of the plate 82, to a position at least as low as the lower edge of the counterpart carton.

Examination of such FIGURES 16, 17, 18 and 19 shows the presence of the outwardly flared flanges at opposite sides of the hinge between the skirt and the plate 82. Such flanges, when provided, serve to provide abutments against which the descending carton will ride during its movement, thus somewhat tilting such carton away from the plate 82, and aiding in reversal of the angle of support of the carton on its shelf, prior to delivery from such shelf.

Referring to FIGURES 39 to 44, inclusive, I have therein shown a modified embodiment of the skirt structure. In FIGURE 39 the several successive lower edges of the steps of the plate 82 are shown, and the skirts 111, 112, 113, 114, 115, 116 and 117 of the modified embodiment are shown in their relation to such barrier plate 82. In this form, each such skirt comprises a length of thin sheet material of elastic characteristics, formed into U-shape, with the V-portion of such U drawn into a slotted portion of slot width to receive the thickness of the plate 82 with a gripping force. The two arms 118 and 119 are then flared outwardly from such U-shaped portion 120, at angles such as shown in FIGURE 40. The plate 82 is slotted just above the lower edge of each of its steps, by a horizontal slot of lateral dimension sufficient to receive one of the flared arm units, which unit may set into place through such slot by inserting one of the arms 118 or 119 through the slot, and shifting the element into intended position by endwise movement through the slot until the U-shaped portion comes to the location of such slot. Then, as a final phase of such inserting movement such U-portion may be forced into place to bring the sides of its U into engagement with the opposite faces of the plate 82 just below the location of the slot. Then the spring nature of the material from which such unit is made will produce a gripping force on the plate 82 between its lower step edge and the location of the slot to ensure retention of the skirt element in its intended position.

In order to stiffen the two arms of such skirt unit, if desired, such arms may be longitudinally crimped as shown at 121; but such crimping is in such case terminated just below the U-portion, thus avoiding impairment of the spring nature of the gripping against the faces of the plate 82. If desired, the slot 122 may, in such case, be provided with a central vertically enlarged portion 123, as shown in FIGURE 43; but in some cases such vertical enlargement will not be needed, since the spring nature of the skirt material will enable deformation of its cross-section sufficiently during insertion through the slot, to enable such insertion through a straight slot. The

stiffening of the arms 118 and 119, will ensure good engagement of the portion 120 against the faces of the plate 82, since thereby the rocking movements of such arms will be produced substantially at the lines of bend of the arms with respect to the U-portion 120.

Examination of FIGURES 5, 6, 10, 15 and 23, and others, shows the presence of down-bent lips 125 at the far sides of the ejector receiving notches, such lips being formed on the lower flanges 56 of the shelf elements. 10 These lips are provided to ensure against possible damage to the cartons being loaded onto the shelves. The following explanation is now in order respecting such loading operations:

Comparison of FIGURES 3 and 15, and others shows 15 that each shelf, when loaded, supports its group of cartons along its length from front to back of the structure, so that such shelf, when originally loaded, carries such row of cartons close together, substantially filling such shelf. In FIGURE 15 the cartons are shown slightly separated from each other, to facilitate explanations based 20 on the showings of that figure; but frequently, or even generally, the cartons when loaded onto the shelf will be closer together than the showing of that figure. A convenient operation for producing such loading consists in 25 setting the cartons onto the front end of the shelf (the door of the cabinet being open for such purpose), and as each carton is set onto the shelf it is pushed back against its neighbor, thus gradually filling the shelf with the intended number of cartons. Evidently such loading operation 30 involves a sliding movement of the already loaded cartons backwardly along the shelf 56, and during such sliding movement each carton must move over a notch 102 of the flange 56. In so doing it must again assume rest on the opposite side of such notch. Any slight irregularity in the edge of such notch, such as a bur left 35 during the manufacture of the shelf, will present a possibility of catching on the bottom portion of the carton, and possibility of producing a sufficient damage to produce a leak of the carton's contents. Due to the very 40 nature of the contents of the cartons, being food products, such as milk and the like, cleanliness of the interior of the storage chamber is imperative. The provision of the downwardly deflected lips 124 greatly reduces the possibility of damage to the cartons during the filling operations, and afterwards.

Referring again to the stepped lower edge plate 82, the same is supported into the frame of the cabinet or other housing in manner such as to enable ready vertical adjustability of such plate to bring its several steps into 50 proper vertical elevations for production of carton releasing and delivering. Since the ejector units act to produce the lateral ejecting movements of the cartons for release from the support of the shelf, it is evident that the vertical position of the lower edge of each of the 55 steps of the plate 82 must be exactly phased with respect to the lateral ejecting operation, to produce the best releasing and delivering operations. The vertical adjustability of the plate 82 makes it possible to bring such plate into exactly correct vertical position, after the ejectors 60 have been installed on the floor of the cabinet or other housing. Accordingly I have provided an upwardly extending flange 126 on the top edge of the plate 82 which is engaged between a pair of downwardly extending flanges 127 connected to the top or roof of the chamber in which 65 the cartons are stored, so that the plate 82 is supported against lateral deflections at its upper end. I have also provided the vertical slot 128 in the lower portion of the front bar 129 which is connected to the front edge of the plate 82. Such bar 129 extends down in proximity to 70 a stationary element 130 of the lower portion of the cabinet. A wing nut or the like 131 may then be extended through the slot into such stationary element, to secure the plate 82 in its position of vertical adjustment. In this connection the following further comments are pertinent:

The best release and delivery of a carton is produced when the ejector arm commences its lateral shift of the lower portion of the carton in correct timing with respect to the lateral support of the upper portion of such carton, produced by engagement of such upper portion with the face of the plate 82; and such optimum delivering operation also includes movement of the carton downward far enough, in comparison with such lateral ejector produced movement, to permit passage of the upper portion of the carton beneath the lower edge of the corresponding step of the stepped plate 82 at the correct phase of the operation. Thus there is required a correct phasing of the movements downwardly and the movements laterally, requiring corresponding proper relative positioning of the several parts of the device. Having established such proper relationship between the stepped plate and the shelf of the carrying unit at one face of such plate (e.g., the carrying unit I, in FIGURE 3), it may be found that correct phasing of the movements at the opposite face of such plate 82 no longer exists, requiring relative adjustment between the positioning of the shelf of the carrying unit II and the previously adjusted plate 82. Such relative adjustment may now be made without changing the vertical elevation of the plate 82, as follows:

I have already described the structure of the drive shaft 67 at the upper end of each carrying unit, and have shown how, by loosening the set screw 75 (FIGURE 9), the chains 62 and shelves of the corresponding carrying unit may be shifted vertically (with corresponding necessary rotation of the sprockets carrying such chains), for bringing the shelves to a new position with respect to the stopping position of the output shaft of the corresponding drive motor. Accordingly, the adjustment of such carrying unit II, with respect to the already adjusted position of the plate 82, may be readily produced when such set screw has been loosened, and the set screw may then be retightened. Such a sequence of adjustments would be especially necessary when the two carrying units were loaded with widely different sizes of cartons as shown in FIGURE 3, wherein the elevation for release of the upper portion of a carton on unit I must be the same as the elevation of the upper portion of the carton on unit II, but wherein the delivering vertical position of the shelf of unit II must then be different from the delivering position of the unit I. It is noted that in the showing of such FIGURE 3 the two cartons are both shown at the same supporting shelf elevations so that one or the other, but not both, of the cartons are in releasing and delivering position.

Study of FIGURE 5 will show that as the shelves there illustrated move down, step-by-step and as release and delivery is made of the cartons successively along each shelf, as hereinbefore explained, the last carton to be delivered from each shelf is the right-hand carton close to the vertical strut 51. Also, that the last carton to be released from the entire rack is that carton at the right-hand end of the lowermost operative shelf, shown as 89 in such figure. That last carton is numbered 132 in FIGURE 5. Accordingly, when such last carton of the carrying unit has been delivered, such carrying unit is out of service insofar as concerns its ability to make delivery of a carton. I have therefore made provision for passing a signal to the proper equipment when such last carton has been delivered, to thus protect the customer from collecting a pre-pay coin which cannot make corresponding delivery of merchandise. Such provision is as follows: Reference is made to FIGURES 5, 6, 6A, 10, 15, 34 and 45.

A vertical rod 132 has its lower and upper end portions journalled in the base element 133 and the bracket plate 134, respectively, such bracket plate being secured to the right-hand vertical strut 51 (see FIGURES 6 and 10). The lower portion of such rod has secured to it a paddle plate 135, whose cross-section is shown in FIGURE 6A. Such paddle plate thus includes the two portions 136

and 137, substantially at right-angles to each other. The upper portion of such rod carries an actuating plate 138, shown in FIGURES 5, 10 and 34. Such actuating plate extends parallel to the paddle plate portion 137, and such actuating plate is rocked back and forth according to the positions of rock of the paddle plate. In FIGURE 34 such paddle plate is shown as acting against a stem 139 which extends through a "motor plate" 140, presently to be described in detail. A normally open switch element 141 is conveniently supported at the back or right-hand side of such motor plate, in position such that when the actuating plate 138 is rocked into its full line position (shown in FIGURE 34) the flexible contact 142 of the switch is retained in engagement with the stationary contact of such switch, thus retaining a circuit element in closed condition. On the other hand, rock of the rod 132 clockwise, when viewed from above, permits such actuating plate to back away leftwardly from the stem 139, thus allowing the switch contacts to be disengaged, opening the circuit. The biased spring condition of such contact 142 will generally be sufficient to retain the stem leftwardly when the rod is rocked clockwise, for such circuit opening operation. Thus, the normal condition of the parts is that in which such rod has been rocked clockwise to swing the paddle plate substantially 45 degrees clockwise from its position shown in FIGURES 5, 6 and 15, with the switch in open circuit condition.

When a carton stands at the extreme right-hand position of the lowermost shelf, as shown at 132 in FIGURE 30, such carton presses against the portion 136 of the paddle plate retaining such paddle plate in its counter-clockwise rocked position, with the rod and actuating plate correspondingly held in switch closed positions, as shown in FIGURE 34. But when such last carton has been displaced from its position on the shelf, the paddle plate is permitted to swing, under force of the spring action, substantially 45 degrees, thus opening the switch and the controlled circuit, presently to be described. Such circuit controls the coin operated devices to either 40 coin receiving condition (carton in place), or coin rejecting and returning condition, simultaneously giving a signal to the customer, as by a light, that such carton carrying unit is empty.

It must be noted, however, that if reliance were to be placed solely on the condition of presence or absence of a carton on the most right-hand position of the lower shelf, the empty signal would be given at conclusion of carton deliveries from each shelf arriving at the lowest, carton delivering position, regardless of presence of cartons on the higher up shelves, not as yet delivered. Accordingly, it will be noted from FIGURES 5, 6 and 15 that such paddle plate 135 has a vertical dimension sufficient to engage the most right-hand cartons on both the lowermost shelf and the shelf immediately above, so that the carton on such immediately higher shelf will prevent swing of the paddle plate for circuit opening, even when the most rightward carton is delivered from the lowermost shelf. Thus, the giving of the signal indicates that both such shelves are empty. If the shelves were all properly filled with cartons before placing the unit into operation, the giving of the signal under the conditions stated above, would indicate complete emptying of the shelves of the carrying unit.

The lowermost sprockets 66 which carry the lower ends of the chain loops, are severally journalled to the lower portions of the struts 50 and 51. Such journal mountings are of form to permit vertical adjustments of the sprockets to bring the chains into desired tension for proper running. To this end the following structural elements are provided, FIGURES 6, 7, 8 and 15.

A plate 144 is set against the outside face of each of the vertical struts, and a companion bracket plate 145 is set against the inside face of such strut opposite to such plate 144. The bracket plate has secured to it a journal stud on which the corresponding sprocket is journalled.

A vertical slot 146 is provided in the web of the strut, and screws 147 are set through the plate 144 and the bracket 145, and through such slot, so that by tightening such screws the plate and the bracket are drawn together to lock these parts against vertical shift. The slot 146 is of vertical dimension to accommodate such vertical adjustments of the sprocket as may be needed, primarily for the purpose of ensuring taut condition of the chain loop. Such vertical adjustments of the sprocket are facilitated by provision of a tension screw 148 extended through a flange 149 secured to the bottom portion of the strut and threaded into a flange 150 comprising a portion of the plate 144. By loosening the screws 147 the plate may be brought to vertically adjusted position, after which the screws may be again tightened to retain the plate in such position of adjustment.

Examination of FIGURES 1 and 2 shows the vertical ribs 151, 152, 153 and 154 secured to the inner face of the door 155 of the cabinet. That door, as will presently appear, is the main door which, when opened, gives access to the entire area of the interior of the cabinet. By opening such door the cartons may be loaded onto the shelves of the several carrying units by any convenient operation, such as setting them individually onto the front portions of the shelves, pushing any earlier loaded cartons back along the shelves during such operations. Thus each shelf may be loaded; but unless care is exercised to press the shelves thus loaded backward along the shelves, it may happen that after loading the final or forward-most carton on some shelf, the group of cartons on such shelf has not been moved fully backward to bring the rear-most carton into engagement with the paddle 135 of the empty switch control element. The ribs 151, 152, 153 and 154 on the door are set at such positions laterally of the door, that when the door is closed each such rib will press against the most forward of the cartons on each of the shelves of the carrying unit behind such rib, thus pressing the group of cartons on such shelf backwardly to the intended positions of the cartons of such group.

Reference has been made to a motor plate which carries the drive motors for the several carrying units. Such plate and various elements directly related to the motor operations, are shown in detail in FIGURES 2 and 32 to 37, inclusive, to which figures reference is now made:

The motor plate 140 is set into the upper rear portion of the cabinet (see FIGURE 2). It comprises a sheet of metal or other suitable material, having its lower edge formed rearwardly to provide the flange 155, which flange is hinged to the plate 156 by a piano type hinge 157, such plate 156 being in turn secured to the sheet 158 comprising a portion of the back wall of the chamber wherein the carrying units are received. Normally the motor plate is secured in its vertical position, shown by the full lines in FIGURE 34, and by dashed lines in FIGURE 2, such securing being produced by wing nuts (not shown) set through the slots 159 along the upper edge of such plate 140; but on occasion, by releasing such wing nuts, the motor plate may be rocked forwardly and down into horizontal position (shown by the fragmentary portion 140^a, in dashed lines, in FIGURE 34). When the plate is thus swung down into horizontal position it will be sustained in such position by engagement of the flange 155 with the face of the sheet 158. Thus sustained in horizontal position the back face of such motor sheet 140 faces upwardly, and is exposed to the view and operations to be performed on elements carried by the back of such motor plate.

Such motor plate is provided with large openings 159, 160, 161 and 162 which come opposite to the locations to be occupied by the several carrying units when the structure is in working condition. Such motor plate is also shown in FIGURE 3 wherein the above relationship of such openings and the several carrying units, is

shown. The upper edge of such motor plate is also provided with the downwardly extending notches 163 and 164 which accommodate the downwardly extending flanges 127 (two pairs), shown in FIGURE 3, and by which the upper portions of the stepped plates 82 are sustained against lateral shift; it being noted that the provision of such notches in the upper edge of the motor plate enables forward and downward rock of the motor plate without interference of the upper edge portion of such motor plate with such stepped plates during such forward and downward rocking operation. Thus it is not necessary to remove such stepped plates during such rocking movement of the motor plate.

A motor carrier plate 165 is set over each of the openings 159, 160, 161 and 162 of the motor plate; each such motor carrier plate being of larger size than the opening which it covers. Each such motor carrier plate is provided with a hole 166 (see FIGURE 34) through which protrudes the output shaft of the corresponding drive motor and its built in speed-reducer. The drive motors and their speed-reducer elements are shown at 167, 168, 169 and 170 in FIGURE 33. Each is securely fastened to the back face of its motor carrier plate, as by the studs 171, 172 and 173 (such stud 173 for the unit 170 being shown in FIGURE 33); such securing being executed to align the low-speed output shaft of the unit centrally of the corresponding hole 166 of the carrier plate. It is thus evident that lateral change of position of the carrier plate on the motor plate 140, with corresponding shift of the position of such output shaft with respect to the motor plate 140, will also produce lateral shift of such output shaft with respect to the motor plate. Since the motor plate 140 is hingedly connected to the stationary structure of the cabinet it follows that such lateral shift of the carrier plate will also effect lateral shift of such output shaft with respect to the cabinet structure. Accordingly, it is possible by such lateral shift of the carrier plate with respect to the motor plate 140, to effect such lateral re-positioning of the 40 drive motor's output shaft as may be needed to bring such output shaft into alignment with the drive shaft fixture 77 at the rear end of the corresponding carrying unit, when such carrying unit is set into a new position, laterally of the cabinet. The means enabling such lateral re-positioning of the carrying unit in the cabinet has already been explained. The foregoing aligning operation is a lateral alignment of the parts. It is also necessary to ensure vertical alignment of the motor's output shaft and the drive shaft fixture of the carrying unit. Such fixture is numbered 77 in FIGURE 9. A collar element 174 is secured to the front face of each carrier plate at the location of each of the shaft openings 166 through which the output shafts project. Such collar element includes a socket 175 extending inwardly from its front end, concentrically with respect to such output shaft opening, with an opening in the floor of such socket aligning with the output shaft opening 166; and such socket 175 is slightly oversize compared to the diameter of the fixture 77, such fixture being of tapered form to facilitate its entry into the socket as the carrying unit is moved backwardly into its intended position within the cabinet. Also, the output shaft is provided with a cross-wise extending pin 176 of length slightly less than the diameter of the socket, such pin being of diameter to set into the slot 78 in the fixture 77. Accordingly, as the carrying unit is moved into its working position, such slot will ride over and receive the pin, thus providing driving engagement from the motor's output shaft to the fixture 77, and thus to the rod 73 of the carrying unit's drive shaft, provided that such rod and the fixture 77 are turned into angular phase such that the cross pin may enter the slot. The drive shaft structure of the carrying unit is shown in FIGURE 9 which has already been described. It will therefore be seen that by loosening the screw 75 of such carrying unit drive shaft, thus

freeing the rod 73 from the tube 70, such rod (and the fixture) may be rotated, if necessary, to bring the slot into phase with the cross pin to enable the assembling operation to be completed; it being unnecessary to produce physical up or down movement of the carrying unit's chains and shelves to produce this operation.

Due to tolerances in manufacture of parts and otherwise, it may happen that as the carrying unit is thus moved backward into its final operating position within the cabinet, there may be a slight misalignment vertically of the parts, so that the fixture 77 does not exactly align with the output shaft of the motor element. To meet this condition I have provided a forwardly extending stud 177, preferably but not necessarily, vertically above the collar 174, such stud having its end tapered as shown in FIGURE 33 at the location of the motor carrier plate 165^a. Such stud is carried by such motor carrier plate, and thus retains a fixed position with respect to the low speed output shaft of the motor. The web of the vertical strut 51 of the carrying unit in question is then provided with a hole 178 at exactly the right position, such that as the backward movement of the carrying unit takes place, such hole will receive the tapered end of the stud, and thus produce exact axial alignment of the motor output shaft, and the driven carrying unit shaft input, to ensure free running of the parts when the assembling operation has been completed. Then, if there should develop any slight mis-alignment of the driving and driven shaft elements, the provision of the slightly yieldable grommet 79 of rubber or other elastic material will permit continued free running of the parts.

The motor elements 167, 168, 169 and 170 are self-contained units, each including the motor 179, the gear reducer 180, and the motor low-speed output shaft already referred to. Each such motor drive unit also includes an electrically released, normally engaged, brake element, which brake element is moved to its releasing position as long as current is being supplied to the motor. Immediately upon termination of such current supply the brake sets, thus locking the motor and its output drive shaft against rotation. Such motor units as just described are well known in the arts, and detailed description thereof is not necessary here. However, the following comments respecting this drive are pertinent;

Examination of FIGURE 3 shows that the loading of the cartons and their contents on the shelves produces a torque urging rotation of each of the carrying unit drive shafts in direction of rotation corresponding to descent of the loaded side of the carrying unit. No counter loading force is produced on the opposite, rising run of the chain loop, so in order to prevent a run-away condition, allowing the weights of the cartons and contents to descend freely and without control, some means must be provided to prevent such run-away condition. The drive motors are of high speed type, of the order of 1,800 or 3,600 r.p.m., so a large gear ratio must be provided between the motor armature and the output shaft. Such gear ratio must be high enough to drive such output shaft so slow, even with the high armature speed, that an appreciable length of time will elapse between commencement of a releasing and delivering operation, and conclusion of such operation. That time element should be of the order of several seconds. Furthermore, during such releasing and delivering operation the output shaft makes only a partial rotation (one-seventh in the case of loading seven cartons along the length of the shelf element); thus the time element needed to make such one-seventh of a rotation of the output shaft must be consumed during only one-seventh of a rotation (substantially 51 degrees and 25.9 minutes of arc). Or, again, the gear reduction must be of the order such that several seconds are consumed in driving the output shaft only through such arc as stated. If the unbalance of torque condition produced when the cartons and contents are loaded on their shelves, is sufficient to overcome fric-

tional and other resistances, it is evident that the run away condition may occur; but such resistances, in conventional forms of such gear drives are such that it is practically impossible to reverse drive the motor armature by torque delivered at the output shaft (low speed shaft). Thus a self-locking condition is produced, ensuring against run-away conditions. However, a further condition is to be considered, as follows:

Due to the high speed of armature rotation of such motor, the inertia (rotational) of such armature and connected gear elements is sufficient to require an appreciable amount of time to stop the elements when current is cut off at completion of a releasing and delivering operation. Even so small a time element as a part second would, 10 under such conditions, result in an appreciable angular rotation of the output shaft after cut-off of the current. This would result in stoppage of the entire chain loop and all of the shelves, slightly beyond their proper stopping stations. This would, in turn, result in stoppage of 15 the now or next to be delivered shelf slightly beyond its position of phase registry with the corresponding ejector unit and arm. It would also result in a slight over-run of the cam element, presently to be described, carried by the output shaft 166^a of the motor unit, and which 20 controls a switch comprising a portion of the motor control circuitry. For the foregoing and other reasons it is desirable that immediately upon termination of current supply to the motor, the output shaft should be 25 positively locked against further rotation to carry such shaft beyond its intended angular position. The means to terminate current supply each time the motor drive has advanced the chain loops the proper distance to correctly phase the shelf exactly with the position of the 30 ejector arm next to be actuated is as follows:

To the low-speed output shaft 166^a carries a disk cam element 181 having a number of notches 182 equal to the number of cartons to be accommodated on a shelf element, such notches being spaced equidistant from each other as shown in FIG. 37. A normally open switch element 183 is supported by a stationary part in proximity to such cam element, such switch element including the stationary spring contact 184, and an outwardly biased flexible spring contact 185 whose bias normally holds such contact free of the stationary contact 184. 35 Such biased spring contact 185 carries an inwardly extending stud 186 of insulating material which normally engages the periphery of the cam element. When the cam element has come to position of registry of any one of its notches with such stud, the latter is permitted to rock leftwardly into such notch, with corresponding opening of the motor control and other circuits, to bring the motor to rest by cutting off its current supply. Such rest condition will occur until the circuit for current supply 40 to the motor is again closed momentarily by another switch element, thus bringing the motor again into operation, and carrying its stud rightwardly to now close the motor circuit at the position of such switch 183. The motor circuit will then remain closed until the next 45 notch comes to the position of the stud, whereupon leftward rock of the stud and contact will again occur, with corresponding opening of the motor circuit, the other switch element above referred to having been closed for only a short time, to give a short impulse closure to the circuit, for starting purposes only. The circuitry of which 50 such switch element 183 comprises a part is shown in FIGURE 45, presently to be described.

Since such cam is located directly on the low-speed output shaft 166^a of the motor unit of the carrying unit in question, which motor output shaft is directly drivingly connected to the sprocket shaft of such carrying unit, it follows that very close control of the stoppage of current supply to the driving motor for the carrying unit in question is attained, with corresponding accuracy of control of the stoppage of the shelf movement at the proper 55

position with respect to the corresponding ejector unit. It is here noted that when it is desired to change the device for accommodation of a different number of cartons on each of its shelves, the cam of such carrying unit must also be changed to a cam which is provided with a number of notches equal to the new number of cartons to be accommodated on the shelves of such carrying unit. Such change can be conveniently made by use of elements such as previously disclosed herein. Thus, by releasing the upper edge of the plate 140 and swinging it forwardly and downwardly (the carrying units having been previously removed), all of the drive motor units will be exposed, being now supported in vertical shaft position. Thus, proper substitution of one or more new cam elements for those previously carried by the motor output shafts, can be easily made. Other changes or substitutions of operative elements may also be made with such plate 140 in such horizontal position; and such other operations will be referred to hereinafter. Reference has already been made to the provision for giving an empty signal when all of the cartons of a carrying unit have been released and delivered. The means to produce such empty signal include the stem 139 which extends through the plate 140, as shown in FIGURE 34. It is here noted that prior to turning the plate forwardly and down into its horizontal position, the carrying units have been removed from the cabinet. Therefore the actuating plate 138 has been carried from its position proximate to the stem 139 so that such actuating plate does not interfere with the forward and downward rock of the motor plate 140.

Reference has been made to the need of producing lateral adjustment of the low speed output shaft of each drive motor corresponding to lateral adjustments of corresponding carrying units. In FIGURE 32 there are shown the upper and lower holes 187 and 188 above and below the opening 160, and close to the right-hand edge of such opening. There are also shown the pairs of holes 189-190 and 191-192 above and below such opening 160, and close to the left-hand edge of such opening. Suitable screw elements, such as wing nuts may be threaded into certain of such holes to secure the corresponding carrier plate in place with respect to such opening 160. For this purpose the carrier plate (shown for each of the openings 159, 161 and 162, but not shown for the opening 160 in FIGURE 32) corresponding to each such opening is provided near its top edge with vertical slots as shown in FIGURE 32, corresponding to the openings 159 and 161, and corresponding to the openings 160 and 162, and is also provided near its lower edge with companion vertical slots. Such upper slots are numbered (for the carrier plate 165^a) as follows: At the left-hand side of such carrier plate, the upper and lower slots carry the numerals 193 and 194, respectively; at the righthand side of such carrier plate, the two upper slots carry the numerals 195 and 196, and the two lower slots carry the numerals 197 and 198, respectively. I have referred to the carrier plate for the opening 162, as above, since the carrier plate for the opening 160 is not shown in place; and for the further reason that the two carrier plates for the openings 159 and 160 are for carrying units at opposite faces of one of the plates 82, and thus must serve carrying units of reversed facing, while the two carrier plates for the openings 161 and 162 are also for carrying units at opposite sides of another of the plates 82, and thus must also serve carrying units of reversed facing. But for the foregoing reasons it is seen that both of the carrier plates for the openings 159 and 161 are duplicates, and both of the carrier plates for the openings 160 and 162 are duplicates. Thus, by describing the carrier plate for the opening 162 in relation to the opening 160 I am also describing that carrier plate embodiment which properly fits the requirements imposed by the opening 160, in comparison

with that opening 160. Bearing the above in mind, it will be seen that the carrier plate for such opening 160 may be set into either of two positions laterally with respect to such opening, as follows:

5 Rightward setting of the carrier plate, with the plate openings 193 and 194 matched with the holes 189 and 191, and with the openings 195 and 197 matched with the holes 187 and 188;

10 Leftward setting with openings 193 and 194 matched with the holes 190 and 192, and with the openings 196 and 198 matched with the holes 187 and 188. The lateral displacement of the carrier plate effected by such rightward or leftward shifting, is made to correspond with the lateral change in position of the carrying unit, 15 so that the position of the low speed output shaft of the corresponding drive motor unit will match the laterally displaced position of the carrying unit. Since the empty signal controlling elements (including the paddle 135, the rod 132 and the actuating plate 138) comprise portions of the carrying unit which has been considered as laterally shifted, it follows that the proper relationship between the actuating plate 138 and the stem 139, and the empty signalling switch 141, remain proper for their intended functions.

20 25 Reference is next invited to FIGURES 1, 2, 3, 4, and 38 which show various structural features of the cabinet or other housing for the previously detailed units, and also show the refrigerating arrangements, the arrangements for producing the desired circulation of cooling air through 30 the storage chamber, the various door elements and devices carried thereby, and the hopper construction wherein the released and delivered cartons are held until the vend delivery door is opened by the customer to gain access to his purchase.

35 40 45 The cabinet includes the storage chamber 199 which has been previously referred to. This is enclosed by walls 200, and 201, back 202, top 203 and bottom 204, all including ample heat insulation materials, according to conventional practice. The front main door 205, hinged to the front portion of the side wall 201, extends from the top 203 to a position lower than the chamber 199, so that it also encloses the refrigerating cell 206 which houses the air cooling unit of conventional form, 207, which is supplied with the refrigerant fluid from a compressor unit housed in the compressor chamber 208 below the bottom 204 of the refrigerating cell. Examination of FIGURES 1 and 2 shows that the main door 205 also extends down far enough to overlie the compressor chamber 208, although the door sealing gasket 209 which assures air tight seal when the door is closed extends down only far enough to ensure such door sealing of the enclosures which are refrigerated.

50 55 60 The air cooling unit 207 includes the conventional cooling coils 210 enclosed in a suitable housing, together with the circulating fan 211 driven by the fan motor 212. An air box 213, located at the air output face of the cooling unit (its rear), is provided with a top outlet flue 214 which seats into the lower opening of the hood 215 just below the floor of the chamber 199. The fan draws intake air from the front portion of the cooling chamber, cools it, and delivers the cooled air upwardly into the hood.

65 70 75 The back wall or partition of the storage chamber 199 is shown at 216 (see FIGURE 2). It comprises substantially the rear frame elements of the carrying units, and is thus substantially open throughout its height to the location of the space 217 behind the motor plate 140. Thus the cooled air supplied upwardly from the hood 216 rises through the space 218 between the partition 216 and the heat insulated rear wall 202, some of the rising air flowing laterally into the storage chamber at various elevations, so that there is a substantially uniform flow of such cooled air into the back portion of the storage chamber throughout the height of such chamber. Por-

tions of such cooled air also flow between the upper portion of such partition 216 and the motor plate 140 to the extreme top of the storage chamber. In such chamber such cooled air swings forwardly and downwardly to return through the open floor of the storage chamber, such floor or partition comprising chiefly the various structural elements by which the lower portions of the carrying units and the plates 82 are supported. Thus there is free access of such returning air into the cooling chamber 206 for re-cooling and re-circulation. A thermostat element, presently to be referred to again, is installed in the flue or air box 213 to constantly test the temperature of the air being delivered from the cooling unit and prior to entrance of such air into the storage chamber. Such unit is shown at 219 in FIGURE 38, connected by a flexible cord to the plural contact electric plug fixture 220 in that figure. From such plug fixture connections are established to the circuitry, to ensure locking of the proper elements when the air temperature rises above an established high point, to thus prevent sale and delivery of any of the cartons until a proper examination of the contents of such cartons shall have been made, and for other reasons. Such an established high temperature for cut-out is 50 degrees F.

At the level of the floor of the storage chamber I have provided a downwardly and forwardly slanting chute element (see FIGURES 1, 2, 3 and 38). This chute is broad enough to receive cartons delivered from any of the carrying units and from front to back of each such unit. The cartons descending to such chute then slide down and forwardly on the chute for delivery into a delivery hopper under control of the door element 221. The chute is identified as 222 and the hopper is identified overall by the numeral 223. The door element 221 is hinged horizontally to the lower edge 224 of an opening 225 in the lower portion of the main door 199, so that delivery of the cartons from the device is made by rocking such door element 221 outwardly through an angle of substantially 40 degrees into the dashed line position 226 shown in FIGURE 38. Since the door thus gives access to the refrigerating cell 206 such door is sealed, when closed by the soft gasket 227 to prevent needless loss of cooling effect.

The hopper 223 is hinged at 228 close to the bottom of the opening 225, but at the inside or cell end of such opening. This hopper is connected to the inside face of the door 221 by a link 229 pivoted to the door at the point 230, and pivoted to the hopper at the point 231. Preferably there is one such link at each side of the hopper, thus producing a balanced structure. The pivotal connections of the link to the hopper and to the door are so located that during out-swing of the door in the opening direction, such hopper is also rocked from its normal carton receiving full line position in FIGURE 38, to its dashed line position in that figure. In such full line position it is evident that any carton descending along the chute must fall into the hopper, since under the stated conditions the rear wall of the hopper is far enough rearwardly to prevent a carton from passing between such rear wall and the lower edge of the chute. On the other hand, when the door open position has been attained the rear wall of the hopper has come into position such as to prevent unauthorized reaching backwardly through the door opening, and through the body of the hopper into the lower end of the chute. Thus, with the door opened fully it is impossible for a person to reach up into the lower portion of the storage chamber for loosening an unpaid for carton. But with the door in such fully opened position it is possible for the person to reach into all portions of the hopper for extracting the properly delivered cartons from such hopper. The safety barrier plate 232 is secured to the under face of the top of the door opening 225, and extends rearwardly far enough to prevent an unauthorized person from gaining access to the lower portion of the chute when the door has been

only partially opened, but does not interfere with back and forth rocks of the hopper produced by closing and opening door operations.

A drain for condensation water is provided in the 5 floor or partition 210, as shown at 233; and a water barrier 234 is provided, across the said floor, to prevent movement of such condensation water forward to the door opening 225.

A vertical passage 235 is provided behind the back 10 wall of the refrigerating cell, for accommodation of various electrical lines between the refrigeration cell and the compressor chamber 208 and other locations.

The refrigerant fluid connection between the compressor element in the compressor chamber 208 is shown at 15 236 (see FIGURE 2). This line extends down into the compressor chamber (see FIGURE 4) and connects into the compressor unit 237 (see FIGURE 4), the details of which unit need not be stated here as such units are of various types and conventional in principle of operation. At the location where such line 236 extends past 20 or through the floor 204 between the refrigerating cell and the compression chamber, provision has been made to facilitate removal of such line from such floor without disconnection thereof from either the refrigerating unit 25 or the compressor unit. To this end I have provided the rearwardly extending recess 238 in the edge of the floor 204 (see FIGURE 4), and such line 236 is set back into such recess and held there in convenient manner, when the device is in operation. Whenever it is desired to 30 remove the compressor unit as I shall presently explain, such line may be drawn forward out of the recess, leaving the line still connected to both the compressor unit and the refrigerating unit. The compressor unit is carried by a base plate 239 so that the entire compressor 35 unit may be slid forwardly far enough to gain access to its various parts, for adjustment or replacement as needed from time to time.

Examination of FIGURES 3, 2 and 4 shows that the 40 refrigerating unit occupies a position in the refrigerating cell, back of the lower portion of the chute 222, and behind the door 221. Also, examination of FIGURES 1 and 3 shows that the upper side portions of the chute element are provided with the outwardly extending flanges 240 and 241 which are slidably set into the 45 horizontal, rearwardly extending slotted openings between angle bars supported by the side walls of the device. Thus, by moving the door 221 into non-interfering position, the chute may be slid forwardly and removed from the device, to thus clear a path for removal by forward movement of the refrigerating unit. Such movement of the door into non-interfering position may be produced by disconnection of the two links 229 from the door by drawing out the pivotal pins 227.

The main door of the cabinet, 205, is provided with 55 a central secondary door element 242 hinged by the vertical piano type hinge 243. This secondary door carries on its back surface, various circuitry elements related to the coin controlled operations and otherwise; and other circuitry elements may also be accommodated within a recess of the main door, which recess is covered by the closing of the secondary door. Since these elements of circuitry are shown in or related to the wiring diagram shown in FIGURE 45, I shall not here refer in detail to them. However, it is noted that included in 60 such circuitry is the selector switch by means of which the purchaser may select that type of carton and contents which he desires to have delivered. Such switch is actuated by the hand grip 244 which may be turned to either of four positions, corresponding to the four carrying units already described. The proper coin for pre-payment may be inserted at the slot 245. The signal lamp 246 will light when payment is made for delivery of a carton from a carrying unit which is empty; and upon pressing the lever 247 laterally the pre-payment coin or coins will be released and returned to the cup 65 70 75

248. The signal lamp 249 may be connected into the circuitry in manner proper to give some other specified signal, as for example, that payment shall be made only by insertion of a dime.

The flight-shelf support by the chains is such that the shelves are sustained against tilt which would cause release of the cartons during the down movement of such shelves to the discharge position. Thus, each shelf is so supported during its downward travel that it cannot tilt in carton releasing direction. In the embodiment of carrying unit thus far described such support is produced by the twin rollers 63 and 64 journaled on the pins 59 and 60; and in such previously described embodiment such pins are secured to the end plates 57 of the flights in such manner that the shelf is retained both against downward tilt and against possible upward tilt. This is because such pins are both secured to such end plate. With this embodiment it is evident that during the rise of the flights at the back sides of the carrying units the flanges 55 and 56 must project laterally at the back sides of the carrying units. This fact is shown at the left sides of FIGURES 7 and 12, and at the right sides of the companion FIGURES 8 and 14. Accordingly, the overall width required to accommodate each of the carrying units must be sufficient to take care of the extra space (width) needed to accommodate such projecting portions of the flights.

In FIGURE 46 I have shown another embodiment of the flight supports to the chains, by which it is possible to avoid lateral projection of the shelf flanges beyond the necessary space required to meet the width of the chains themselves, during the returning or rising travels of the flights at the back sides of the carrying units. The showing of this FIGURE 46 is schematic, but in sufficient detail to show the structure as well as the mode of operation of the embodiment. In this case only one of the pins 60 or 59 is actually journaled to the end plate 57 of the flight, being, in such embodiment, the lower pin 60. Then such end plate 57 is cut back as shown at 250 in FIGURE 46, to provide an abutment edge which will engage the pin 59 to resist rock of the flight beyond that position, with respect to the chain, in which the flanges of the flight are horizontal. Thus, examining the central right-hand (downward moving) flight in FIGURE 46, it is seen that load carried by the flange 56 produces a clockwise torque tending to rock the flight clockwise; but the extent of such rock is limited by engagement of the abutment edge 250 with the upper pin 59. This condition will continue until the chain advance has proceeded far enough to carry the flight around the lower sprocket 66 (the load previously carried by the flange 56 having been discharged), to bring the center of gravity of the flight directly below the pivot pin 60. Such center of gravity is shown by the black dot in each of the flight showings of FIGURE 46. Such condition is shown for each of the flights rising at the left-hand or back side of the carrying unit of FIGURE 46. It is noted that until the flight comes substantially to the position "C" the pin 59 is still in engagement with such abutment edge; but that further progress of the travel to the position in which the pin 60 is riding up along the tangent or stretch of the chain travel, causes such pin 59 to move away from such abutment edge, leaving the flight hanging solely on the pin 60 as a pivot. Return of the pin 59 into engagement with such abutment edge will occur as the flight travels up and around the upper sprocket 65-69.

It is evident, however, that rock of the flight counterclockwise about the pivot point 60, from the engagement of the edge 250 with the pin 59 may continue, if need be, to the point of engagement of the edge of the plate 57 with the pin 59 at a point close to the flange 56. Such an engagement condition would represent an extreme amount of counterclockwise rock of the flight.

For clarity I have designated the center of gravity of

the flight in each of the illustrated flight positions, by the numeral 251 with the suffix "a," "b," etc., to conform with the designations of such several positions by the letters "A," "B," etc.

5 Following the successive movements of the chains and a typical one of the flights of FIGURE 46, the following comments are pertinent:

In position "A" the flight is supported against down tilt of its flange 56 by engagement of the edge 250 with the pin 59. This condition continues during down movement of the chain to the location of the lower sprocket 66, being termination of travel downwardly on the tangent. During this time the center of gravity lies to the right of the vertical position through the pivot pin 60, so the gravitational effect of the flight produces torque clockwise about such pivot point. As the pins 59 and 60 move clockwise around the lower sprocket 66 position "B" of the flight shows that the center of gravity is acting most strongly to urge clockwise rock of the flight, restrained only by the continued engagement of the edge 250 with the pin 59. Finally, at the position "C" the center of gravity has moved to a position directly beneath such pivot pin 60. At this point the pin 59 is still in engagement with the edge 250, but without reacting pressure. 10 Such pin 59 will move away from the edge 250, leaving the flight pendant solely on the pivot pin 60. As the flight then enters the back tangent and commences its upward travel it will, unless restrained by an outside force, continue upwardly without change of angular position 15 20 25 30 35 40 45 50 55 60 65 70 75

In FIGURE 46 I have shown the drive shaft 67 for the upper sprockets, as previously described herein. It is seen that just prior to attaining the position "F" the back 57 of the flight has come into engagement with such shaft, thus producing an interference in the progress of the flight. As the flight then proceeds clockwise around the sprocket 65-69 such engagement between the back 57 and the shaft, produces a rock of the flight into the position "F," with its tip portion of the flange 56 executing a circular movement on the arc 253. Further clockwise travel will bring the flight to the position "G." It is noted that during travel from position "F" to position "G" the edge 250 remains uniformly away from the pin 59 until a position such as "G" is reached. During this travel from "F" to "G" the center of gravity has continued to lie to the left of the vertical projection through the pivot pin 60, so the developed torque retains the back 57 in engagement with the shaft. At about the position "G" the center of gravity has moved slightly over and to the right of the line projected through the pivot pin 60 so the developed torque reverses, acting to rock the flight on its pivot pin 60 clockwise into the position "H." This rock occurs without any needful movement of the chain and pins 59 and 60 clockwise around the sprocket 65-69. Such rock then carries the edge 250 rightwardly against the pin 59 to the position 250^h in FIGURE 46. Thereafter, further travel around the sprocket 65-69 and downwardly along the right-hand tangent will occur with the center of gravity rightwardly of the pivot pin 60, thus retaining the edge 250 in engagement with the pin 59, to sustain the shelf against down rock, and to sustain the load carried by the flange 56.

In FIGURE 46 I have shown, schematically, by the dashed line 254, the surface of a baffle plate which may be supported just leftward of the chains which carry the flights. Such baffle, when provided, serves to limit the leftward swing of the flange 56 of each flight, as shown at "J" in FIGURE 46. Such retaining of the flight against further clockwise rock, and corresponding limitation of the leftward movement of the flange 56, causes portions of the flight to infringe upon the position of the shaft 67 between the upper sprockets. Accordingly,

when using such a baffle, and when such baffle is carried up as far as shown in FIGURE 46, the shaft 67 must be eliminated between the two sprockets at the two ends of the flights. Any other suitable means may be adopted for driving the two sprockets synchronously and in phase, such as the provision of a back shaft high enough to avoid the arc 253, together with positive drives between such back shaft and both sprockets. Conversely, by terminating the baffle below the elevation where the presence of the shaft 67 becomes effective to rock the flights 56 outwardly, the lateral dimension needed for accommodation of the flights during travel up to the position of such limitation, may be reduced by use of such limited dimension baffle. In FIGURE 46 such baffle has been carried high enough to control the outswing of the flange 56 during flight travel to and past the position "K" shown in such figure.

It will be understood that in the various figures of this case, other than FIGURE 46, I have shown journalling provisions for both of the lower sprockets, and without need of any shaft directly connecting together such sprockets.

It will be understood that the flights of the embodiment shown in FIGURE 46 are provided with the necessary recessing to accommodate the ejector units such as shown elsewhere in this case, or other ejectors suitable to produce the desired release of the cartons from the flanges 56, all according to the principles set out at length herein.

In FIGURE 46 I have shown a cross-section through one of the flights of embodiment just described, for simplicity of illustration of such embodiment.

In FIGURE 48 I have shown another embodiment of the end portion of the flight. In this case the upper pin 59' is used as the pivot pin, the end flange 58' being journalled thereon. In this case the end plate 58' is cut away from back towards the front of the flight, to provide an edge abutment 250' against which engagement of the pin 60' occurs to limit rocking of the flight clockwise. Nevertheless, such flight may rock counterclockwise, carrying the edge abutment 250' rightwardly from such pin 60'. By cutting away the back plate 57' at the location of such cut-away portion of the end plate interference of such back plate 57' with the pin 60' is avoided, thus removing limitation of the permissible rock of the flight counterclockwise, due to engagement between the pin and such back plate.

It is to be understood that when using the embodiment of flight shown in FIGURE 48, such flight may be provided with the necessary recesses 102 to accommodate the ejector unit stands 98 already described. It will also be understood that although I have, in various figures, shown the successive ejector stands 98 as of progressively less height, progressing from left to right in various figures, all such stands may, if desired be made of the full height of the most leftward or forward of such stands, being designated 98^a in FIGURES 5, 6 and 15, since the ejector arms 104^a and their pivotal points 100^a may then be located at the proper heights in each of the several stands. Thus the manufacture of all of the stands may be standardized of such maximum height.

I claim:

1. In a carton dispensing device, a dispensing unit including two vertically extending companion loops of tension material and upper and lower loop supporting wheels for each such loop, the supporting wheels for the two loops being located in positions opposite to each other and with the vertical runs of the two loops included in vertical parallel planes, means to advance the wheels of the two loops in synchronism step-by-step and in the same rotational direction, a series of horizontal flights extending between opposing positions on the runs of the two loops which runs of the two loops travel in the same direction during each step-by-step advance of the wheels, means to connect the two ends of each flight to the loop runs at such opposing position, each flight including a

carton supporting flange extending out horizontally from the plane which includes the loop runs, the means which connects the two ends of each flight to the loop runs being constituted to retain such flange in horizontal position when carrying the weight of a carton, with the flange extending outwardly from the plane of the loop runs in direction substantially normal to such plane during movement of such flange to a carton delivery position on the downwardly moving run of the loops to which the flight is connected, carton delivery means including an ejection finger, pivot means for said finger located at an elevation higher than the carton delivery position of the flange with the finger depending from said pivot means and located behind the carton, said pivot means being constituted for swing of the finger in a plane substantially normal to the plane of the loop runs, a cam element on the finger, a cam engaging element on the flight adapted to engage the cam element of the finger when the flight is at a position proximate to the carton delivery position, the cam element being constituted to swing the finger in its plane of movement in carton delivery direction during downward movement of the flight to the carton delivery position.

2. In a carton dispensing device, the dispensing unit as defined in claim 1, wherein the means which connects at least one end of the flight to the proximate loop run includes two pins each engaging both the loop run and such end of the flight, said pins being separated from each other and parallel to each other.

3. In a carton dispensing device, the dispensing unit as defined in claim 2, wherein the engagement of each pin with both the loop run and the flight end is constituted to retain the pin and the engaged element against lateral movement with respect to each other.

4. In a carton dispensing device, the dispensing unit as defined in claim 2, wherein the engagement of one pin with both the loop run and the flight end is constituted to retain such pin and the engaged element against lateral movement with respect to each other, and wherein the engagement of the other pin with one engaged element is constituted to retain such pin and such engaged element against lateral movement with respect to each other, and wherein the engagement of such other pin with the other engaged element is constituted to engage such other engaged element in manner to retain such other pin and such other engaged element against lateral movement in direction corresponding to down rock of the flight from its position normal to the plane of the loop runs during movement of the flight on the downwardly moving run of the loops to which the flight is connected.

5. In a carton dispensing device, the dispensing unit as defined in claim 2, wherein the engagement of one of the pins to the loop run and to the flight comprises a pivotal connection between the loop run and the flight, permitting rocking movement of the flight with respect to the loop run, together with an abutment in position for engagement with the other pin when the flight extends outwardly from the plane of the loop runs in direction substantially normal to such plane to resist rock of the flight downwardly from such normal outward extension during movement of the flight on the downward moving run of the loops to which the flight is connected.

6. In a carton dispensing device, a dispensing unit including two vertically extending companion loops of tension material and upper and lower loop supporting wheels for each such loop, the supporting wheels for the two loops being located in positions opposite to each other and with the vertical runs of the two loops included in vertical parallel planes, means to advance the wheels of the two loops in synchronism step-by-step and in the same rotational direction, a series of horizontal flights extending between opposing positions on the runs of the two loops which runs of the two loops travel in the same direction during each step-by-step advance of the wheels, means to connect the two ends of each flight to the loop runs at such opposing positions, each flight including a

carton supporting flange extending out from the plane which includes the loop runs, the means which connects the two ends of each flight to the loop runs being constituted to support such flight when carrying the weight of a carton, with the flight extending outwardly from the plane of the loop runs in direction substantially normal to such plane during movement of the flight on the downwardly moving run of the loops to which the flight is connected, together with carton delivery means constituted to shift a carton laterally on its flight in direction away from said plane of the two loop runs, said delivery means comprising a rock arm, means to pivot such rock arm in position for rocking sweep of the arm transversely of the flight and across the carton occupying space in direction of sweep away from the plane of the loop runs, and cooperating elements on the rock arm and the flight constituted to cause the rock arm to execute such sweep during downward travel of the flight substantially at the release position of the carton from the supporting flange of the flight.

7. In a carton dispensing device, the dispensing unit as defined in claim 6, wherein the means to pivot the rock arm comprises a substantially vertical stand and means to support such stand stationary in proximity to the vertical path of travel of the flight downwardly at the carton release position.

8. In a carton dispensing device, the dispensing unit as defined in claim 7, wherein the flight carton supporting flange is provided with a recess extending from the release edge of such flange towards the plane which includes the two loop runs, and wherein the vertical stand is in vertical alignment with such recess and the recess is of size and contour to accommodate the stand during downward travel of the flight.

9. In a carton dispensing device, the dispensing unit as defined in claim 6, wherein the means to pivot the rock arm includes a pivot element above the carton supporting flange when such flange is at the carton releasing position together with means to rock the rock arm outwardly away from the plane of the runs of the loops, comprising a cam element in connection with the rock arm, together with a travelling abutment in connection with the flight in position to engage such cam element during downward travel of the flight, the cam element being of contour to cause delivery swing of the rock arm during downward travel of the flight substantially to the carton release position, and wherein the cam element is of size to permit disengagement of the travelling abutment of the flight at a position of flight lower than the release position of the flight for carton release.

10. In a carton dispensing device, the dispensing unit as defined in claim 9, wherein the flight is of length to accommodate a plurality of cartons in proximity to each other along its length, and wherein the disengagement of the travelling abutment of the flight from the cam of such rock arm occurs with flight movement to a position lower than the carton releasing position of such rock arm and cam element, and wherein the rock arm is constituted to swing into position in alignment with a non-released carton carried by said flight, during engagement of the travelling abutment with the cam element aforesaid, and wherein the disengagement of the travelling abutment aforesaid from the cam element occurs at a position of said flight below the position of release of the carton by said rock arm, from the flight flange.

11. In a carton dispensing device, a dispensing unit including two vertically extending companion loops of tension material and upper and lower loop supporting wheels for each such loop, the supporting wheels for the two loops being located in positions opposite to each other and with the vertical runs of the two loops included in vertical parallel planes, means to advance the wheels of the two loops in synchronism step-by-step and in the same rotational direction, a series of horizontal flights extending between opposing positions on the runs of the two loops

which runs of the two loops travel in the same direction during each step-by-step advance of the wheels, means to connect the two ends of each flight to the loop runs at such opposing positions, each flight including a carton supporting flange extending out from the plane which includes the loop runs, the means which connects the two ends of each flight to the loop runs being constituted to support such flight when carrying the weight of cartons supported by such flange, with the flight flange extending outwardly from the plane of the loop runs in direction substantially normal to such plane during movement of such flight on the downwardly moving run of the loops to which the flight is connected, each flight being constituted to receive and accommodate a plurality of cartons along its length, and all of the flights being constituted to receive and accommodate the same number of cartons with the successive cartons of the flight supported in vertical columns, carton delivery means corresponding to each such vertical column, and constituted to shift a carton of such column laterally on its flight in direction away from said plane of the two loop runs, each delivery means being supported for movement between a carton non-delivery position and a carton delivery position, the delivery means which correspond to the different columns of cartons being constituted for delivery of the cartons from such columns at different vertical positions of a flight and means to support each delivery means at a vertical position corresponding to the vertical position of the flight for delivery of a carton of the column corresponding to such delivery means, from such flight.

12. In a carton dispensing device, the dispensing unit as defined in claim 11, wherein the delivery means for successive vertical positions of the flight correspond to successive columns of the cartons along the flights, and wherein the step-by-step advances of the wheels correspond to movements of the flight to successive vertical positions of the flight for successive delivery of the cartons from the successive columns of cartons.

13. In a carton dispensing device, the dispensing unit as defined in claim 12, wherein each step advance of the wheels corresponds to vertical movement of the flight equal in amount to the distance between successive flights divided by the number of columns of cartons.

14. In a carton dispensing device, a dispensing unit including two vertically extending companion loops of tension material and upper and lower loop supporting wheels for each such loop, the supporting wheels for the two loops being located in positions opposite to each other and with the vertical runs of the two loops included in vertical parallel planes, means to advance the wheels of the two loops in synchronism step-by-step and in the same rotational direction, a series of horizontal flights extending between opposing positions on the runs of the two loops which runs of the two loops travel in the same direction during each step-by-step advance of the wheels, means to connect the two ends of each flight to the loop runs at such opposing positions, each flight including a carton supporting flange extending out from the plane which includes the loop runs, the means which connects the two ends of each flight to the loop runs being constituted to support such flight when carrying the weight of a carton, with the flight extending outwardly from the plane of the loop runs during movement of such flight on the downwardly moving run of the loops to which the flight is connected, together with a vertical carton lateral supporting plate proximate to and parallel to the dispensing unit and separated from the carton supporting flange of the flight a distance to accommodate a carton supported by said flange, carton delivery means constituted to shift a carton laterally on its flight away from the plane of the two loop runs and towards the carton lateral supporting plate, said delivery means comprising a rock arm, means to pivot such rock arm in position for rocking sweep of the arm transversely of the flight and across the carton occupying space in direction

70

75

of sweep away from the plane of the loop runs and towards the carton lateral supporting plate, and means to cause the rock arm to execute such sweep during downward travel of the flight substantially at a carton release position from the supporting flange of the flight, the elevation of the lower edge of the carton lateral supporting plate proximate to the carton release position of the flange constituting a carton top lateral support releasing element, said lower edge being located at vertical elevation for lateral release of such carton top during downward travel of the flight substantially at the carton release elevation of the flight flange, together with means to support the vertical carton lateral supporting plate with its carton top lateral release lower edge at said vertical position.

15. In a carton dispensing device, the dispensing unit as defined in claim 14, wherein the elevation of the lower edge of the carton lateral supporting plate is vertically adjustable.

16. In a carton dispensing device, the dispensing unit as defined in claim 14, wherein the dispensing unit and the vertical carton lateral supporting plate comprise companion carton supporting and releasing units, and wherein the lateral separation between such units corresponds to the size of cartons to be supported by and released from the flights, and wherein the means to support at least one of such units includes means to support such unit at different amounts of lateral separation between the units, corresponding to different sizes of the cartons to be supported by and released from the flights.

17. In a carton dispensing device, the dispensing unit as defined in claim 14, wherein each flight of the dispensing unit is constituted to receive and accommodate a plurality of cartons along its length, and wherein all of the flights are constituted to receive and accommodate the same number of cartons with the successive cartons of the flights supported in vertical columns, and wherein there is carton delivery means corresponding to each such vertical column and each constituted to shift a carton laterally on its flight in direction away from the plane of the two loop runs, and wherein each delivery means is supported for movement between a carton non-delivery position and a carton delivery position, and wherein the delivery means which correspond to the different columns of cartons are constituted for delivery of the cartons from such columns at different vertical positions of a flight and there is means to support each delivery means at a vertical position corresponding to the vertical position of the flight for delivery of a carton of the column corresponding to such delivery means, from such flight, and wherein the lower edge of the carton lateral supporting plate is provided with successive edge portions in lateral alignment with the columns of cartons, each such lower edge portion being at an elevation corresponding to lateral release of the carton top of a carton of the corresponding column during downward travel of the flight substantially at the carton release elevation corresponding to such column of cartons.

18. In a carton dispensing device, the dispensing unit as defined in claim 17, wherein there are two of the dispensing units located at opposite side faces of the carton lateral supporting plate, and wherein the vertical runs of the two dispensing units, and the flights connected to such vertical runs, which vertical runs are proximate to the carton lateral supporting plate, advance downwardly for step-by-step advances of the wheels of the two dispensing units, and wherein the carton delivery means for each such dispensing unit moves the corresponding carton towards such carton lateral supporting plate, and wherein the dispensing units are supported at elevations such that the lower edge portions of the carton lateral supporting plate are at elevations corresponding to lateral release of the carton tops of either of the dispensing units.

19. In a carton dispensing device, the dispensing unit as defined in claim 14, together with a downwardly ex-

tending skirt element in connection with the lower edge of the carton lateral supporting plate and extending downwardly substantially as far as the elevation of the flight at carton release therefrom, the connection of such skirt to the lower edge of the carton lateral supporting plate being constituted to permit lateral swing of such skirt during carton release and delivery from the flight.

20. In a carton dispensing device, a dispensing unit including two vertically extending companion loops of tension material and upper and lower loop supporting wheels for each such loop, the supporting wheels for the two loops being located in alignment with each other in pairs, each pair of wheels being aligned on an axis normal to the planes which include the loops, a series of horizontal flights extending between and connected to opposing positions on the runs of the two loops which runs of the two loops travel in the same direction during loop advances, each flight including a carton supporting flange shelf extending outwardly from the plane which includes a run of both of the loops, a drive shaft for one pair of wheels, said drive shaft comprising a wheel supporting tube on which the wheels are mounted, driving connections of the wheels to such tube, a drive rod extending axially through the tube from a driving position at one end of such rod to a driven position beyond the wheel at the other end of the rod, a rod driving element connected to the rod at the rod driving position, a driving motor in driving connection with such driving element, together with means to releasably connect the driven position end of the rod to the tube.

21. In a carton dispensing machine, the combination of a carton dispensing unit including two vertically extending companion loops of tension material and upper and lower loop supporting wheels for each such loop, the supporting wheels for the two loops being located in horizontal alignment with each other in pairs, each pair of wheels being aligned on an axis normal to the planes which include the loops, a series of horizontal flights extending between and connected to opposing portions of the runs of the two loops which runs travel in the same direction during loop advances, each flight including a carton supporting flange shelf extending outwardly from the plane which includes a run of both of the loops, a horizontal drive shaft for one pair of wheels, driving connections between the wheels and said drive shaft, a rectangular frame enclosing all of said parts, means to journal the drive shaft in said frame, means to support said frame in substantially vertical planar position, said supporting means being constituted to permit endwise movement of the frame in the direction of its plane, together with means to drive the drive shaft including a motor plate, a drive motor including a motor driven output shaft, means to connect the drive motor to said motor plate with the output shaft substantially normal to the motor plate, means to support the motor plate, said supporting means being constituted for movement of the motor plate between a dispensing unit drive shaft driving position in which the motor output shaft and the dispensing unit drive shaft are in alignment with each other, and a dispensing unit drive shaft non-driving position in which the motor output shaft and the dispensing unit drive shaft are not in alignment with each other, and means to couple the motor output shaft and the dispensing unit drive shaft together when said shafts are in alignment with each other.

22. In a carton dispensing device, the dispensing unit as defined in claim 21, wherein there is a plurality of the dispensing unit frame supporting means constituted for support of the frame at different lateral positions, and wherein the means to support the motor plate is constituted for support of the motor at different lateral positions corresponding to the different lateral positions of the frame of the dispensing unit, and wherein at each such lateral position of the motor plate the motor output shaft

is contained in the same vertical plane which contains the dispensing unit drive shaft.

23. In a carton dispensing device, the dispensing unit as defined in claim 21, wherein there is a plurality of said dispensing units, and wherein the means to support the frame of each dispensing unit is constituted for support of such dispensing unit facially parallel to the other dispensing units, with the successive dispensing units supported at successive laterally separated positions from each other, and wherein there is a drive motor corresponding to each of the dispensing units, and wherein there is means to connect each drive motor to the motor plate, each such connecting means being constituted for lateral

adjustment of the corresponding drive motor to position of alignment of the output shaft of such drive motor, laterally, with the drive shaft of the corresponding dispensing unit.
